ACCOUNTING MACHINE FOR REPEATING
TOTAL PRINTING CYCLE WHEN ERROR IN
ACCUMULATOR RESET IS ASCERTAINED

Edward J. Rabenda, Ralph E. Page, and Horace S. Beattie, Poughkeepsie, N. Y., assignors to International Business Machines Corporation, New York, N. Y., a corporation of New York

Application September 14, 1948, Serial No. 49,256

9 Claims. (Cl. 235—61.7)

1

This case relates to accounting machines and more particularly to the type in which the printing of a total is automatically initiated, and thereafter there is an automatic accumulator reset operation.

Machines of this type receive their entries from their amount controlling records, such as perforated records, and the machine is conditioned, at times, to take a total from an accumulator. This conditioning of the machine is usually effected by an automatic group control device. In this cycle of machine operation the total is printed, and then the accumulator is automatically reset so that it may be able to receive further amount entries.

Machines of this type are in wide commercial use and are efficient and highly accurate in their operation so as to perform the desired mathematical and statistical computations. However, at times due to the neglect of the operator, such as the failure to make a required plug connection, the accumulator may not be reset to zero and thus the next series of entries will be incorrect. Other less frequent reasons for this misoperation may be due to mechanical difficulties, such as the failure of a part to function properly, the wearing out or maladjustment of the parts, etc. but whatever the reason the required high accuracy of such machines demands that such failures in operation be indicated and corrected.

It is, therefore, the main object of the invention to automatically test the digit position of each order of an accumulator after it has been reset to determine if all orders are at their reset position.

A still further object of the invention is to repeat the reset of the accumulator in the event that an order of the accumulator has not reached its reset position as a result of a reset operation and to then indicate this fact to the operator.

A still further object of the invention, especially when the accounting machine is provided with a total printing mechanism, is to test the reset position of an accumulator after the total digit representation thereof has been printed and to automatically repeat the total printing operation if it has been ascertained that one or more orders of the accumulator have not reached the reset position.

A still further object of the invention especially when the present invention is embodied in a record controlled accounting machine, is to automatically test each order of an accumulator after a reset operation to determine whether each accumulator wheel has reached its reset posi-

2

tion and in the event that an error has been detected, repeat the reset operation and then produce a desired signal.

Another object of the invention relating to the preceding object is to automatically suppress the feeding of cards whenever it has been ascertained that the reset position of an accumulator wheel has not been reached, and signal this fact to the operator by suppressing card feeding operations to thereby suppress accounting operations under control of the next group of records.

Another object of the invention, when the present invention is incorporated in a record controlled accounting machine with automatic total printing and resetting operations, is to repeat the total printing in the event that an accumulator order has not reached that position as a result of a reset operation and to further suppress the feeding of records of the next classified group so that the reason for the error can be ascertained.

Another object of the invention relating to the preferred specific construction is to employ in each accumulator order the transfer contacts for reset test purposes and to transmit an impulse after a reset operation serially through such contacts to determine whether each accumulator order has reached the reset position. One advantage accruing from this construction makes it possible to initiate and carry out this reset test in a short time at the end of a total printing and reset cycle so that according to the result of the test the machine operations may continue in a normal manner or machine operations may be modified.

Other objects of the invention will be pointed out in the following description and claims and illustrated in the accompanying drawings, which disclose, by way of example, the principle of the invention and the best mode, which has been contemplated, of applying that principle.

In the drawings:

Figs. 1-17 pertain to the card feeding and analyzing unit wherein:

Fig. 1 is a detailed sectional view showing one of the magnetically controlled clutches.

Fig. 2 is a left side elevation view of the entire card sensing unit.

Fig. 3 is a plan view of the driving connections to the main operating shafts and the connections from the clutches thereon.

Figs. 21a, 21b, 21c and 21d constitute the timing charts.

Figs. 22a and 22b when assembled comprise a side elevational view of one order of the printing mechanism and also show the rotary translator and converter for converting combinational hole impulses derived from the accumulator readout to a differential timed equivalent.

Fig. 23 is a side elevational view showing the gearing for the drive shafts shown in Figs. 22a and 22b.

Card analyzing mechanism

The card analyzing mechanism used in connection with the group control mechanism of the present embodiment of the invention is shown and claimed in the application of R. E. Page et al., Serial No. 768,639, filed August 14, 1947.

The main purpose of the machine is to sense the code perforations in the machine control element C (Fig. 16) and initiate timed electrical impulses representative of group control data thereon. In so doing, the machine feeds the records successively out of a magazine and thence successively to two sensing stations.

At each of the sensing stations the card is halted momentarily and sensed electromechanically, while in a static condition. At the two sensing stations, the devices cooperating with the card are substantially the same, and the purpose is to effect the controls commonly known in the art and often referred to as upper and lower stations, between which a group control device can function in a well known manner to test whether successive records belong to the same or different groups by comparisons of group control designations thereon.

In the present case, the identifications U and L are applied to the right and left stations, respectively, because they correspond in effect to the usual upper and lower sensing stations of a tabulator, the former of which is known as a

control station mainly because of the group control function connected therewith and the latter of which is known as the adding and printing control station because the impulses therefrom are usually directed into accumulators and print control magnets.

In each sensing station there are electro-mechanical devices comprising a full set of vertical sensing pins, one for each index point position on the card. The pins are normally held elevated until a card stands in the sensing position, and then the pins are lowered so that certain of them project through perforations and the others remain elevated or raised on the imperforate portions of the card. Cooperating with the heads of each column of pins are three contact levers or bell cranks, the one arm of each crank having a cam face which rides over the heads of the seven related pins and, when a pin is in the depressed position, the crank is allowed to rock to close a contact. The cranks are all mounted on a common reciprocating frame which is oscillated over the pin holder after each depression of the pins.

In station U, it is noted that there are only three sets of sensing cranks, one for each deck of sensing pins. The other station L differs in that the cranks associated therewith are arranged in four sets, the extra set forming a function of sensing what is termed the "late 5" impulse. The reason for such an arrangement is to conform with the construction of accumulating and printing devices which require, for example, for the addition of 9 to have one or more impulses distributed over a wide range of time greater than that provided between the code positions 5 and 0 in this present considered 7-hole code. Therefore, in the addition of a large digit (i. e., a digit greater than 5) it is provided that two cranks cooperate in the sending of impulses to make up the entry of the large digit. This purpose is not only true of the extreme end position, wherein cooperate the two cranks at one side of the sensing unit, but all four sets of cranks have some joint cooperative entry action for the entry of what may be termed early and late 5 values. For example, the first and second cranks cooperate, the second and third cranks cooperate, and the third and fourth cranks cooperate in their entry of values. In other words, cranks in the outer positions have a single purpose, entering either early or late values while the two sets of centralized or intermediate cranks serve a double function in cooperation with two sets of sensing pins. Since the item entering is not involved herein, it is only generally explained.

Framework

The mechanism is supported on a base upon which is fastened a pair of side frames 26, 27 (Fig. 4) between which the majority of operating parts are suspended.

Extending across the space between the side frames are a number of braces comprising two main castings 28 and 29 (Figs. 6 and 7) acting as bearings for most of the lower feed rollers. Other bracing means is provided by a bar 33 (Fig. 1) acting as supports for the magnet units of clutch mechanisms. Near the forward end of the frames there is fastened a cross bar 35 (Fig. 1) which holds the contact members of the circuit breaker devices.

Poised above the driving mechanisms are a pair of pivoted units, one carrying most of the sensing mechanism and the other carrying the stacker drum and receiving hopper. These two

pivoted joints are positioned wherein the first is folded under the second. When they are both swung to the open position, access is obtained to the interior of the card feeding mechanisms for adjustment, replacement and repair. When the parts are to be returned to the normal operating position, the sensing device frame is lowered first and then the stacker frame is pivoted over it and latched in a normal sloping position.

The sensing unit frame comprises a pair of heavy side frames 38 and 39 (Figs. 2 and 5) pivoted on studs 40 extending from the outside of the main frames 26 and 27. Attached to the short ends of the lever frames 38 and 39 are studs 42 to which are attached heavy springs 43 tending to rock the sensing frame clockwise to the open position. These springs 43 are not strong enough to lift the sensing unit and merely act as counterbalance means for preventing too sudden dropping of the sensing unit into position. These springs are fastened to studs 44 extending from the front ends of the side frames 26 and 27.

The entire sensing unit is insulated from the remainder of the machine by special attaching means between the levers 38 and 39 and the rest of the unit extending over the card feeding mechanism. The special attaching means comprises rivets 46 (Figs. 8 and 12) which are completely sheathed with insulation bushings and washers 47 for holding the auxiliary side frames 49 and 50 (Figs. 2 and 5) to the main pivoted lever frames 38 and 39. At the plane of contact between frames 38 and 49 and 39 and 50, which would ordinarily be metal-to-metal contact, there are interposed sheets of insulation 52 (Fig. 12) and 53 (Fig. 8) for further prevention of electrical conduction between the sensing unit and the remainder of the machine.

It is sufficient to note, at this point, that the swinging sensing unit frame carries all the sensing mechanism directly above the card, i. e., the sensing pins, the sliding cranks cooperating with said pins, and the contact plates with which the sliding cranks make contact. When the unit is lifted, direct access is given to the card path and the card in transit is revealed in cooperation with the upper and lower feeding rollers, so that anything wrong with the card or the feed devices may be observed and corrected without disassembling any parts.

Extending between the swinging levers 38 and 39 is a tall casting 55 (Fig. 7) tipped at an angle of about 20° to form one wall of the magazine M. Below this casting 55 is a bar with a fixed adjustable throat 56 through which the cards pass successively as they are picked from beneath the stack in the magazine.

The card stacker is supported on a separate frame secured to the main side frames 26 and 27. Referring to Figs. 2 and 5, it is seen that the stacker side plates 58 and 59 are secured to the rear end of the main side frames by means of a series of screws 60. Extending outside plates 58 and 59 are bushings 61 and 62 (Fig. 9) forming pivotal supports for the stacker drum shaft 63, on which is pivoted the frame for receiving the stack of cards. Directly inside the plates 58 and 59 is the pair of pivotally mounted plates 65 (Fig. 5) and 66 (Fig. 2) which are supported on the bushings for shaft 63 and designed to be rockable about that center.

Secured to the inner faces of pivotal plates 65 and 66 are spacers 67 and 68 (Fig. 9) to the

inside of which are secured the grooved runners 69 (Fig. 5) and 70 (Fig. 2) in which the movable card stacking end weight 71 rides. Stacking weight 71 rests against the right face of the stacked cards as viewed in Fig. 2 and, as the cards are stacked, the end is advanced slowly towards the right along the slanted path defined by the grooves in runner guides 69 and 70. A base plate 73 (Fig. 2) is secured to the underside of the runner guides 69 and 70 to support the lower edges of the stack of cards. Underneath the left side of this base plate is a cross bar 74 (Fig. 6) secured not only to the base plate but also to the side plates 65 and 66 to stiffen the entire structure.

Driving mechanism

Since the devices under consideration are designed particularly for card handling and sensing operations, it is apparent that they are adapted for coordination with various types of machines, in fact, any machine suited for control by records carrying data indicia representations.

In Fig. 3, showing a representation of the driving mechanism, the driving gear 110 is operated in a clockwise direction to drive the present card feeding and sensing unit.

Gear 110 driven by card feed shaft 109 meshes with the main driven gear 111 which is fastened to the main driving shaft 112. Mounted on shaft 112 and alongside the inner face of the right side of frame 26 is a connecting gear 113 in mesh with an idler gear 114 pivoted on a bolt 115 secured to frame 26. Gear 114 also meshes with another gear 116 fastened to a secondary drive shaft 117 at a position adjacent the inner face of frame 26. Shaft 117 revolves freely in the main side frame and extends beyond the left side of frame 27 and has secured thereon a series of three circuit breaker operating cams 118, 119 and 120.

Freely mounted on the secondary drive shaft 117 is a clutch drum or spool 125 which is connected to shaft 117, whenever a gate is to be operated to release a record card for advancement, said record card at the time being under the second sensing station L after sensing has taken place. In other words, whenever the record card is released for stacking operation, not only is the gate lowered to allow its advancement but gearing connections are established by the same clutch to initiate movement of the stacker drum to pick up the card due to the connections about to be described.

Carried on the clutch spool 125 is a gear 126 (Fig. 3) in mesh with another gear 127 fastened to a stacker driving shaft 128 extending across the machine and projecting outside the right side frame 26. Secured to the right end of shaft 128 is a gear 129 in mesh with an idler gear 130 which is part of a compound set of gears including a smaller gear 131, both of said gears being loosely pivoted on a bolt 132 extending outwardly from the right side frame 26. In mesh with the smaller gear 131 (see also Fig. 5) of the compound gears is a gear 134 fastened to the right end of the stacker drum shaft 63, which is pivoted in the stacker side plates 58 and 59. By means of the driving connections already noted, the stacker drum SD is rotated in a clockwise direction far enough to pick up a card and deposit it on the stacker tray for each revolution of the clutch spool 125.

It is already mentioned how the main driving shaft 112 is operated by cooperation between the outer driving source as represented by gear 110

7 and the main driving gear 111 fastened to the shaft. Shaft 112 carries a clutch spool 140, said clutch being provided primarily for the purpose of opening the gate which stops the record card under the first sensing station U. In other words, just as the clutch spool 125 serves to control operations in connection with the second gate of the sensing station L, the clutch spool 140 serves to cooperate with the stopping gate of the other sensing station U. This clutch related to spool 140 serves a fourfold purpose, in that it not only regulates the opening of the gate for advancement of the card beyond the first sensing station, but it also has mounted thereon a pair of complementary cams 142 and 143 (Fig. 3) for operating the picker knife to advance records successively out of the magazine. A third control by a cam thereon over a card lever is noted hereinafter. The fourth function performed by the clutch spool is that of operating a circuit breaker shaft by means of a gear 144 fastened to the spool. This gear is near the inner face of the left side frame 27 and meshes with a large gear 146 of a pair of idler compound gears including a smaller gear 147, both being connected by a hub which is loosely mounted on a bolt 148 secured to frame 27. Gear 147 meshes with a gear 149 which is fastened to the circuit breaker shaft 150 extending between the main side frame and used to carry the camming devices for controlling the opening and closing of picker contacts P used to regulate the general operating conditions of the machine.

It is noted hereinbefore that the two clutch spools 140 and 125 are mounted on the front and rear drive shafts, respectively, for the purposes of operating the two gates to regulate the advance of the record. There are two other clutch spools loosely mounted on these same shafts for the purpose of elevating and lowering pin holding devices. One clutch spool 153 is loosely mounted on the main driving shaft 112 and carries a cam 154 which is effective whenever the clutch is operated to raise and lower the pin holder poised above the card in the first sensing station U. The other clutch spool 156 is loosely mounted on the secondary drive shaft 117 and carries a cam 157 which operates devices for raising and lowering the pin holder cooperating with the record card standing in the second sensing station L.

A pair of complementary cams 162 and 163 (Fig. 3) are fastened to the main driving shaft 112 just outside the outer face of the right main side frame 26 and adjacent to the main driving shaft gear 111. These two gears are used to rock a frame which carries the pin sensing cranks back and forth horizontally to sense the heads of the raised and depressed pins cooperating with the perforated records.

Feed roller drive

Fig. 4 is a plan view showing diagrammatically the main driving connections to the feed rollers for advancing the records successively from right to left from the magazine to the stacker. The main driving connection to the feed rollers is established through a compound gear made up of gears 165 and 166 (Fig. 4) joined by a hub 167 which is loosely mounted on a stud 168 extending from the outside of frame 26. The compound gear is mounted as an idler between the main drive gear 111 in mesh with gear 165 and two driven pinions 170 and 171 in mesh with the other gear 166. Pinion 170 carries the driving connections to the preliminary upper feed while the other pinion 171 carries the driving motion

15 to the left through the successive sets of feeding rollers leading to the stacker.

Considering first the feed rollers associated with the card as it leaves the magazine, it is noted that pinion 170 is connected to another gear 172 (Fig. 5) and also fastened to the shaft 173 which carries the pair of first feeding rollers 174 and 175 which engage the lower surface of the card as it appears out of the magazine. This shaft 173 is mounted in fixed bearings in the main side frames 26 and 27, and cooperating with the rollers 174 and 175 (Fig. 4) thereon is a pair of upper rollers 176 and 177 mounted on a shaft 178 which is in turn supported on the ends of arms 179 and 180 pivoted at 181 and 182 on studs fixed to the side frames 26 and 27, respectively. A pair of springs 183 attached to the ends of arms 179 and 180 tend to rock the arms downward, so that the feed rollers 176 and 177 are forced against rollers 174 and 175 to hold the card between the two sets of rollers. The springs also serve to rock shaft 178 so that a gear 184 on the right end of shaft 178 is maintained in mesh with the gear 172 fastened to the other feed shaft 173. These last mentioned rollers cooperate with each issued card as soon as it extends beyond the throat of the magazine and serve in an almost positive manner to advance the record up to the first pair of impositive skid feed rollers wherein the card is merely urged towards the first gate where it is merely held there by frictional contact between feed rollers rather than a strong driving action, such as that exercised by rollers 174—177.

35 After the card leaves the magazine and the first set of rollers associated therewith, it is advanced successively through six sets of rollers before being clipped on the stacker drum. Each of these six advancing means comprises a lower pair of rollers which are positively driven and an upper pair of rollers spring-held against the lower rollers. The six sets of lower rollers are driven successively through idler gears between the various shafts, and the drive is originated at the forward end of the feed unit through the drive gear 166 in mesh with a pinion 171 which is fastened to a shaft 190 carrying the first pair of lower rollers 191 and 192. This shaft 190 (Fig. 4) as well as the other five shafts 193, 194, 195, 196 and 197 are all loosely pivoted in bearings in the two main side frames 26 and 27 and they all extend beyond the left side frame 27 and carry pinions to receive the driving action which is communicated through idler gears. Starting with a pinion 199 which is fastened to the left end of shaft 190, the drive continues successively to the other feed roller shafts through connections including idler gear 200, a pinion 201 on shaft 193, an idler gear 202 and a pinion 203 on shaft 194, an idler gear 204, a pinion 205 fastened to shaft 195, then through an idler 206 and a pinion 207 fastened to shaft 196 and finally through an idler 208 to the pinion 209 fastened to the end of the last feed roller shaft 197. The idler gears 200, 202, 204, 206 and 208 are all mounted on studs secured to the left side frame 27.

70 Since each feed roller shaft is provided with a pair of lower driving rollers, it is believed well to identify these rollers separately. Rollers 211 and 212 are on shaft 193. Rollers 213 and 214 are fastened to shaft 194. Rollers 215 and 216 are on shaft 195. Rollers 217 and 218 are attached to shaft 196. The final pair of rollers 75 219 and 220 is attached to shaft 197.

It will be understood that the card rides over the six pairs of positively driven rollers shown in Fig. 4, and that these rollers underlie the margins running parallel with the two ends of the card. Cooperating with each of these twelve rollers is a smaller upper skid roller resting thereon and adapted to bear down on the upper surfaces of the card to pinch lightly the marginal area between the skid roller and the positively driven lower roller.

It is understood that each of the upper rollers will be urged by a small spring 223 (Fig. 6) attached to the arm 223 (see also Fig. 11) which carries the roller and exerts a slight amount of pressure to draw the small upper feed roller down into contact with the card and the lower roller, so that a frictional driving connection is established, tending to advance the record but failing to exert any appreciable force against a record which is stopped by a gate.

Card magazine and picker mechanisms

The bunch of record cards which are to be analyzed are placed in the magazine and there they are picked off successively from the bottom of the stack and sent through the feeding rollers. The cards are placed in the stack face down with the lower part of the "A" deck leading and the first column at the right-hand side, when looking at the feed unit from the magazine end.

It is already noted that the magazine includes a front wall or vertical plate 55 which is tipped at an angle to define the starting points of the front edge of the cards in the magazine. Attached to this wall 55 is a pair of wings 235 (Fig. 5) for guiding the side edges of the cards as they rest in the magazine. The lower portion of the magazine comprises a large casting 236 (Fig. 6a) which extends across the machine between main side frames 26 and 27 and is secured thereto by a number of screws.

Attached to the top of the casting 236 is a pair of guides formed with horizontally dove-tailed grooves for receiving the slides 243 carrying the picker knife frame as shown in Figs. 7 and 9. The picker knife 245 is adjustably secured on a block 246 which has a plunger 247 extending therefrom into the slide 243. A set screw in slide 243 locks the plunger 247 in position to hold the entire horizontally sliding structure together. The floor of the magazine is not parallel with the base of the machine but is tipped at an angle of 20° to form an angle of 90° with the front wall of the magazine.

Referring to Fig. 7 it is seen that the picker slides 243 are formed at the lower edge with a series of rack teeth engaged by a respective sector 265 fastened to a shaft 266. Two sector arms 265 and 267 are attached to shaft 266 in positions wherein the teeth thereon cooperate with the rack teeth on the underside of the two picker slides 243. Attached to the extension of shaft 266 is an operating arm 270, to which is articulated a link 271 extending rearward (Fig. 1) and at its other end pivotally attached to a stud 272 on the top arm of a lever 273 pivoted on shaft 274 and provided with a pair of rollers 275 and 276 cooperating with the pair of complementary cams 142 and 143 already mentioned as being attached to the clutch spool 140. Whenever the clutch is connected to open the first gate to permit advancement of records, the cams are rotated and lever 273 is rocked in a clockwise direction, pushing on link 271 and rocking both sectors 265 and 267 in a counterclockwise

direction to advance the picker slides 242 and 243 and knives 245 connected therewith to pick off the lowest card and advance out through the throat and into the bite of the first set of feeding rollers 174-177.

The throat is the narrow opening through which only one card may pass at the same time. This opening is defined by adjustable plate 56 already mentioned and a roller 279 (Fig. 7) with its center in alignment with the inner wall defined by plate 56. Plate 56 is fastened to a cross bar 280 which is independent of the front wall member 55 and is made removable, so that if any cards become jammed at the throat the throat plate and bar 280 are easily taken out of the way by removing screws through the stationary side frames 26 and 27.

Roller 279 (Fig. 7) which defines the bottom side of the throat is pivoted in a plate 281 which is guided by a pair of ribs 282 (Fig. 9) on the top face of the magazine casting 236 and is secured thereon adjustably by the screw slot connection 283.

An upper card guide 285 (Fig. 7a) is provided in association with the first upper feed rollers 176 and 177 encountered by the record card as it leaves the magazine. This card guide is formed with an upper vertical portion which is secured to the throat bar 280. Guide 285 is cut out to provide room for the upper feed rollers, and it curves downward in the path the record must take in going from an angle of inclination of 20° down to the horizontal path extending across the sensing mechanism.

Another card guide 286 is provided to define the lower portion of the curve card path between a magazine and first sensing station. This guide 286 is cut out around the lower feed rollers 174 and 175 and has a vertical section which is attached to the wall 287 forming part of the main magazine casting 236.

A card lever is provided in the shape of a long lever 298 (Fig. 2) fastened to shaft 299 and provided with an upper shoe 300 projecting through an opening in the lower card guide 286. Lever 298 is normally held with the shoe 300 retracted downward out of the card path. However, whenever the machine is in a running condition, a cam 250 (Fig. 2) on the clutch spool 140 operates to allow counterclockwise motion of lever 298, and then it projects upward through guide 286 unless held down by a card in passage between the magazine and the first sensing station. Shaft 299 extends outside the left frame 27 (Fig. 2) and carries an arm 251 for holding a pair of contacts 252 in a closed condition. Whenever the lever fails to sense the presence of a card during running condition, it operates the pair of contacts 252 to open them for the purpose of stopping the machine.

The card stops

Associated with each sensing station is a card stop or gate mechanism for stopping the card in position to be analyzed by the sensing pins. There are two such gate mechanisms; one for station U and the other for station L. They are similar in construction and operation so that the description applied to the first gate mechanism associated with station U also applies to the other stopping mechanism as station L, the difference between the two being pointed out in Figs. 6 and 7, where the first cross bar or gate member is designated 310 and the second stop is designated 311.

The two gate mechanisms are self-contained, being mounted in separate castings like 312 in Fig. 7 which fit between the main side frames 26 and 27 and are fastened thereto and act as a sort of basket to hold the studs and shafts for operating the gates 310 and 311 to lift and lower them at proper times to stop and release the cards. These castings also serve to support plates 315 and 316 (Figs. 6, 7 and 9) upon which the card rests as it is being analyzed in two sensing stations. Reference to Fig. 7 shows that plate 315 is situated in sensing station U and is perforated with a complete set of circular openings to underlie all pin positions in the index positions of the card in the three decks. The plate is enlarged at 317 (Fig. 9) to provide for an extra column of perforations which are outside the area of the regular index points mentioned in connection with the card. These extra pin positions at 317 are provided merely for detection of the presence or absence of the card and the card is never perforated in such position. The other plate 316 is similarly constructed with an extension 318 with a set of extra sensing positions for control purposes only.

Turning now to consideration of the construction of the first casting 312 (Fig. 12) and the mechanism hung thereon which is similar to that at the second station, it is noted that the section through the casting (Fig. 7) includes an elongated U-shaped section 321 (Fig. 12). When observed from the other direction in the end sectional view (Fig. 12), it is noted that intermediate the main side frames the casting 312 is formed with an inverted elongated U-shaped section from which there rises three webs, two, 324 and 326 only being shown in Fig. 12. These webs are cut out to allow room for the lower feed roller shafts 190 and 193, but they are elevated in other positions to lie directly under the guide plates 315 (Figs. 6 and 7) for supporting the card in the sensing position.

Referring to Figs. 6 and 9, it is noted that the casting is formed with a pair of forwardly extending ears 329 which serve as bearings. Bolts 330 are pivots for a pair of arms 331 that carry the cross bar or gate 310. In Figs. 6 and 9 it is seen that the gate 310 extends across most of the sensing unit and at its ends is formed with a pair of bent sections at right angles to the elongated portion, said ends not only being formed with a pivot 334 but also extending downwardly as an arm 335, the lower end of which is articulated at 336 and the end of an operating arm 337 fastened to a shaft 338. In the side view it is noted that the construction is such as to lift and lower the gate 310 in an almost vertical path. The parallel linkage is arranged to cause such movement because the fixed centers 330 and 338 are on opposite sides and almost directly in line with the two movable centers 334 and 336. A spring (not shown) which is drawn between arm 337 and a cotter pin fastened to the support casting tends to rock the arm 337 in a clockwise direction with shaft 338. This tendency is also communicated through pivot 336 to the lower extension 235 of the gate 310 which is further guided by the loose pivot 334 on the end of arm 331 pivoted at 330. The control for lowering the gate is exercised by a cam operated arm 342, best shown in Fig. 6, where it is seen to have a roller 343 resting on the gate operating cam 141 (Fig. 3) already mentioned as being on one of the clutch spools which is magnet-controlled.

For further clarification of the means for oper-

ating the front gate, in Fig. 7 the operating shaft 338 extends across casting 312 and is carried by downwardly facing portions of the inverted U section 321. The shaft is held in position by a pair of collars 345 and 346 (Fig. 12). Near the ends of the shaft are secured the lifting arms 337 (Fig. 7) for carrying the two ends of the gate. Near the left end of the shaft 338 is fastened the operating arm 342 with the roller 343 resting on the operating cam 141 (Fig. 3). The cam 141 is so designed that early in each cycle the gate is allowed to rise, as urged by certain springs (not shown), and thereby come up as a stop for engaging a forward edge of the moving card to hold it in the position to be sensed. After the sensing operation is completed, a rise on cam 141 cooperates with roller 343 and rocks arm 342 (Fig. 7) in a counterclockwise direction to depress both support linkages 334 and 337 and thereby lower the gate 310 against the pressure of the springs. The card is then allowed to escape as driven by the skid rollers and continue over to the second sensing station where a similar mechanism for controlling the gate 311 is timed to first hold and then release the record after sensing operations.

Magnetically controlled clutches

Since the gate operating mechanism is controlled by a magnetic clutch, it is believed well at this point to consider the mode of operation of such a clutch. As noted hereinbefore, with reference to Fig. 3, it was explained that four clutches are provided to control the operation of the two gates and to control the operation of the two pin lifting and lowering mechanisms. The clutch spools 148 and 125 are related to the front and rear gate mechanisms, respectively, while the spools 153 and 156 are related to the front and rear pin lifting mechanisms, respectively.

Since the magnetic clutch mechanisms are similar in construction and operation, it is believed sufficient to describe the one associated with the front gate mechanism and such description is understood to apply to the other three clutch controls, said controls being differentiated by the designation of the control magnets, the designations of the control magnets for the front and rear gate mechanisms being designated as controlled by magnets FG and RG, respectively, and the other two pin lifting control clutches being differentiated by designations applied to the magnets FP and RP applied to the controls for the front and rear pin lifting devices, respectively.

In Fig. 1 is seen that attached to the slanted cross bar 33 is a clutch mechanism frame 359 formed with a pair of side walls between which there is supported a shaft 353. This shaft 353 carries the tripping and restoring elements of the clutch which is controlled by magnet FG carried by a bracket 356. A stud 357 acts as the pivot for an armature lever 358 extending upwardly alongside the magnet FG to be influenced when the magnet is energized and deenergized.

Alongside the armature is a stop member 359 provided to limit its movement in the deenergized position. The top end of armature 358 is in the path of a shouldered extension 360 on the end of a tripping lever 361, which is pivoted on shaft 353 and provided at its front end with a hook 362 normally engaging the short extension on a clutch pawl 363 which is pivoted at 364 on a plate 365 attached to the clutch spool 140. Plate 365 is formed with a spring

stud extension 366 from which there extends a spring 367 attached to the end of pawl 363 and tending to rock the pawl into engagement with a single toothed drive disk 368 attached to shaft 112. Since the pawl 363 is normally held out of engagement by lever 361, shaft 112 normally rotates without carrying the clutch spool along therewith. However, when magnet FG is energized armature 358 is rocked clockwise to be disengaged from the shouldered end 360 of lever 361; thus permitting the lever to rock in a clockwise direction about shaft 353 as it is urged by spring 370. The hook 362 then releases pawl 363, so that it may be rocked counterclockwise by spring 367 and drawn into engagement with the single toothed disk 368 and thereby connect the clutch spool 140 to the shaft 112 so that it is carried around thereby with the cams for a single revolution.

Means are provided for limiting the rotation for a single revolution. Pivotedly mounted on shaft 353 are a pair of arms, the one numbered 373 being placed alongside the release lever 361 and having an off-set extension 374 overlying the top of lever 361 to influence its movement in a downward restoring movement. The other arm mounted on shaft 353 is the downwardly extending bar 375 carrying a roller 376 in engagement with a restoring cam 377 which serves to rock arm 375 in a counterclockwise direction about pivot 353, so that a spring 379 attached thereto pulls down the arm 373 which, through the overlying off-set connection 374, exerts a similar downward movement to the clutch lever 361 so that the hook 362 thereon is in the path of the short extension on pawl 363 to stop it at the end of a cycle. Arm 373 is so proportioned that its end confines the projection 380 formed on plate 365 in conformity with the short extension on pawl 363. When the clutch spool arrives in the stopping position as determined by the hook 362, the end of arm 373 snaps down behind extension 380 and prevents rebound.

Lever 375 is held in cooperation with cam 377 by a light spring 382 which is connected to a short arm 383 extending therefrom. This spring 382 is to be differentiated from the stronger spring 379 which is normally relaxed and is stretched in a positive manner to effect declutching action.

Associated with the ends of the armature 358 and the shouldered portion 360 of the clutch lever 361 is a small bell crank 385 which serves to rock in a clockwise direction to disengage the armature in a positive manner from the magnet holes from the time the clutch lever is restored to the home position. This is done to insure the proper latching position of the armature and to overcome any residual magnetism tending to hold it in operating condition.

It will be noted in Figs. 11 and 12 that a long card guide rail 280 is provided near, and attached to, the right side frame 26. It is toward this rail that the upper skid rollers 226 are tilted to direct the card to ride along with its right side edge in a groove cut along the rail.

The liftable sensing frame

It is noted early in this description that pivotally mounted on pins 40 (Figs. 2 and 5) projecting from the main side frames 26 and 27 there are arms 38 and 39 carrying the entire upper sensing structure as a hinged unit. Reference to Figs. 2 and 5 reveals that arms 38 and 39 do not extend forward very far but have insulated

connections with a pair of plates such as plate 50, as described before, to which plates there is secured the large basket frame or main swinging casting 395 in which all sensing and analyzing parts are suspended. Plate 50 is secured to arm 39 by rivets 46 and frame 395 is hung on the same plate by large bolts 396. At the other side (Fig. 5) the frame is secured to arm 38 in a similar fashion by plate 49.

Frame 395 (Fig. 7) carries six sets of pins 398, each set comprising 60 columns with seven pins in a column to analyze the six decks of perforations in two cards at the U and L stations. The pins are arranged in separate groups at the two stations and the holders for them are lowered and lifted separately to project them through the cards intermittently between card movements. Frame 395 also carries seven sets of contact levers or bell cranks 400 which ride over heads 397 of pins 398 to detect lowered pins in perforations and thus close contacts to emit impulses representative of the perforations. There are three sets of cranks 400 at station U with 60 cranks in each set, and each cooperating with the heads of a column of seven related pins. There are four sets of cranks at station L with 60 cranks in each set, the two outer sets of cranks cooperate with but one related set of pins, but the two inner sets of cranks cooperate with two related sets of pins to supplement the impulse initiation with "late 5" readings for accumulation. Frame 395 also holds seven sets of contact strips 407, there being one strip for each crank to carry the electrical impulse which is timed by the crank swinging against it.

In deck B at stations U and L there is an extra column of pins, an extra crank and contact strip to cooperate with an imperforate margin of the cards for presence detection.

Before going into detail regarding the construction and operation of the pin, crank and strip elements of the sensing unit, it is believed best to examine the shape of the swinging frame 395 and how it is adapted to hold such a plurality of elements with diverse movements.

Frame 395 has two side walls 410 and 411 (Fig. 11) which extend from a position near the magazine M to the stacker drum SD (Fig. 9). Tying the walls together are three U-shaped sections, an end section 413 (Fig. 7), a central section 414, and the other end section 415 (Fig. 6). Between the sections are two openings through which the sets of pins reach down to the two cards at the two stations.

Fastened to the tops of the sections are four cam plates 416, 417, 418 and 419 (Figs. 6 and 7), upon which the end cranks 400 ride as they pass beyond related sets of pin heads.

Fastened to the bottom of frame 395 are two thick plates 421 and 422 (Figs. 6 and 7), the former having three elongated openings for the pins at station U and the latter cut out for the pins at station L. Plate 421 has attached to its upper face a thin metal sheet 423 (Figs. 6 and 7) with a complete set of round holes to guide all the pins at station U. Attached to the lower face of plate 421 is a thin card guide sheet 424 (Fig. 7) which is flared upward near magazine guide 285 and extends back to a similar flared sheet 425 (Fig. 6) which is affixed to plate 422 at station L. Both sheets 424 and 425 are cut with a full set of openings through which the pointed ends 399 of pins 398 may pass freely to engage the card surface. The sheets are primarily card top guides and do not guide the pins. To the top of

plate 422 is attached a sheet 426 (Fig. 6) with a complete set of guide holes for the pins at station L.

Referring to Fig. 12, it is seen that a pair of cylindrical sleeves 428 are riveted at the sides to the underside of plate 421 and extend downward to carry the pair of plungers or lifting rods 429 which are used to lift and lower the pins 398. Each rod 429 is shaped with a spacer shoulder 430 on which is fastened the lifting plate 431, which has three elongated openings for the three sets of pins at station U. Lifting plate 431 extends over pins 398 and is carried thereby to be lowered and lifted, so that the pins 398, the heads 397 of which rest on a thin sheet 433 fastened to the top thereof, are dropped into and lifted out of the card perforations.

The sectional view (Fig. 12) shows that the lower end of rod 429 is bored to receive an insulation bushing 435 which is secured thereto by a pin extending through the walls of the pin and the central section of the bushing. This pin 436 extends on both sides and acts as a stop for a spring retainer collar 437 upon which there presses the lower end of a compression spring 438, the upper end of which presses against the lower part of a sleeve 428. A metallic wear plate 440 is attached to the lower part of bushing 435, and it is this button which rests upon an operating roller 441 on the end of an operating arm 442 attached to the shaft 443, which is pivotally mounted on the main side frames. Spring 438 tends to depress the rod or plunger 429 and hold it down against the operating mechanism at all times. In the normal position of the parts the rods are raised to carry the plate 431 and the pins held thereby in an elevated position. Since the pins and the cooperating cranks are to be part of the electrical circuit for initiating impulses, the entire frame must be insulated from the supporting and operating portions of the machine and that is the reason for the provision of the insulation bushings 435 and the insulation plates for electrically separating the main frame 395 from the swinging arms, which are pivoted on the main side frames.

At the right side of Fig. 12 it is seen that the other plunger for rod 429 extending below the right side of the lifting plate 431 cooperates with a roller 445 on an arm 446 also attached to shaft 443. Arms 442 and 446 are, therefore, connected by a shaft 443 and operate together to lift and lower the two rods 429, so that the pin holding plate 431 is lowered and raised in unison at both sides. Alignment is assured because of the guiding effect exercised by the long cylindrical supports 428 through which the rods 429 oscillate.

Fastened near the midpoint of shaft 443 is a third arm 448 which is the operating member carrying a roller 449 in cooperation with the control cam 154 (Fig. 3), which is previously mentioned as being on the clutch spool 153 for the controls over pin lifting devices at the front U station. The contour of cam 154 is such as to hold the pins elevated until a record is at rest in position at station U and then a depression in the cam allows roller 449 to be lowered, carrying the two arms 442 and 446 along therewith in a clockwise direction so that the two rods and the entire set of pins at station U are allowed to descend as urged by springs 438. The pointed ends of the pins then either rest on the top surface of the record card (Fig. 13) or project downwardly through perforations therein (Fig. 15), and it is this gravitational disposition of the pins which

determines the delivery of impulses as effected by the cranks so cooperating with the heads of the pins as to be rocked in and out of contact.

The actual timing of the pin lifting cam 154 is better observed in connection with the timing chart which is to be considered near the end of this specification. The same regard for exact timing of other cams and timing expedients is also considered in greater detail and with more definite regard for timing with relation to the chart discussed hereinafter.

Although the movement of the pins at the first station U was the subject of the preceding section of the description, there is a similar arrangement at station L differing mainly in the operating connections. In Fig. 6, it is noted that at station L there is supported above the sheet 426 a lifting plate 451 similar to the other lifting plate 431. This plate 451 carries a thin perforated sheet 452 upon which rests the edges of all the pins in station L and the sheet is perforated to act as a top guide for the pins. Attached to plate 451 are two rods or plungers (like plungers 429) extending down through guide cylinders 454, said rods and cylinders being similar in construction and operation to the related parts 428 and 429 at station U.

The operating mechanism for the pin lifting devices at station L is somewhat different from those at station U because the drive connections are established through a length of large tubing 456 which encircles a large shaft 457 used to oscillate the crank holding frame. Secured to the middle of the tube (Figs. 3 and 10) is an operating arm 458 carrying a roller cooperating with the cam 157 which is noted in Fig. 3 to be part of the clutch spool 156 already mentioned as part of the assembly for controlling the pin lifting devices at the rear or L station. The timing of cam 157 is noted in the timing chart (Fig. 22a) to be somewhat similar to that of cam 154 for operating the pins at the other station. The operating movement is communicated through the tube 456 to an operating arm 461 (Fig. 6) fastened on the right end of the tube and another operating arm 462 (Fig. 10) fastened on the left end of the tube. These two arms 461 and 462 carry rollers 463 (Fig. 6) cooperating with the lower ends of the two rods 453 extending below the pin lifting plate 451. The action for lowering and raising the pins at station L is the same as that described for station U, since cam 157 is shaped to permit counterclockwise rocking of the two arms to permit lowering of the rods and pins holding plate after a card has been positioned in station L. At the proper time the entire assembly of pins is elevated to permit further advancement of the record into the stacker.

Contact crank shifting mechanism

Before pointing out the means for moving the cranks 400 horizontally to emit timed impulses under control of the depressed pins it is believed best to consider the different positions of the contact making elements, as shown in the enlarged views (Figs. 13, 14 and 15), showing the parts first with the pins 398 in the fully retracted or upper position and then in the position which allows the pins to pass through the holes, and thirdly in a horizontally moved position of the bell cranks over lowered pins.

In Fig. 13 the crank 400 is shown in the normal position related to the associated seven pins 398, which are elevated and it is noted that the first pin at the left acts on a cam end 402 of the crank to

rock it clockwise about pivot 401, so that the contact button 404 is depressed and out of contact with the strip 407.

When the pins 398 are lowered into contact with the card, should the card be imperforate in all positions, then the heads of the pins stand as shown for the first two pins in Fig. 14 and the crank, although it rocks slightly in a counterclockwise direction, still fails for these pins to swing sufficiently to put button 404 in contact with the lower edge of contact strip 407.

It is only when one or more of the pins 398 project through a perforation (Fig. 15) that the head 397 thereof is lowered sufficiently to allow crank 400 to rock in the counterclockwise direction to establish contact with the contact strip. It is not only with the first pin directly under the cam portion 402 that the contact arrangement is concerned, but all seven pins are to be sensed successively and differentially timed impulses caused thereby to control mechanism for adding, etc. For this reason the crank 400 is drawn horizontally toward the right, so that the cam portion 402 is drawn across the heads of the pins from left to right successively. Whenever a depressed pin is encountered by the cam end of the crank the other end of contact button 404 is lifted sufficiently to contact with the underside of contact strip 407 and establish a circuit which is momentarily held should only one pin be depressed, and contact with contact strip 407 is repeated if the next pin is depressed. In this way, any one of seven possible impulses may be delivered for any combination or arrangement of such seven possible impulses as the crank is moved to the right with a uniform motion. The following section of the description is concerned with the means for mounting and shifting the cranks, so that they are adapted to ride over the pins and emit impulses representative of the pin positions as determined by perforations in the record.

All seven sets or rows of cranks 400 are mounted in a common frame for movement in unison over and back across the heads of the pins, there being 60 of said cranks in each row with the exception of two extra cranks cooperating with the pins in the two B decks as shown by the extra set of openings 317 and 318 (Fig. 9).

Reference to Figs. 11 and 12 shows that the crank holding frame has a pair of side bars 465 and 466 in L-shaped formation. Extending across the machine between these two bars are seven comb bars 467 (Fig. 7), each one holding a row of cranks and secured to the top of the horizontal legs of the side bars 465 and 466 by screws 468 (Fig. 12). Thus, the combs 467 not only act as supports for the cranks but they also serve as connecting means and stiffeners for the entire frame which is to be oscillated to give the cranks the necessary movement over the pins.

Since all the comb bars 467 are similar in construction, this description of one applies to the other six. Referring to the end view of Fig. 12, it is seen that the end portions of combs 467 are reduced at the points where screws 468 secure the comb to the end bars 465 and 466. The mid-section is of substantial height to provide stock for several cutting and drilling operations to provide room for the lower parts of cranks 400. As shown in the enlarged views (Figs. 13, 14 and 15), the comb 467 is cut with notches or slots 470, so that each crank 400 has an individual guide around the pivot 401. This pivot 401 is a wire or rod which is extended through circular openings formed in all of the comb teeth 470.

Directed upwardly into the comb bar 467 is a full set of circular openings for receiving small compression springs 471, which press against the horizontal arm of crank 400 and tend to rock it in a counterclockwise direction so that the cam end 402 is directed towards cooperation with the heads of the pins. The horizontal crank arms are guided at the other end by means of a supplemental comb plate 472 which is fastened to the underside of comb bar 467 and formed with teeth which loosely embrace the cam portion of the lever. Extending upwardly from the comb bar is a projection 473 with a front vertical wall which cooperates with a flat face 474 formed at the bend of the upper arm of crank 400 to limit the counterclockwise movement of the cranks, when they are being assembled. It may be noted that the contact button 404 on the end of the upper arm is formed with an arcuate upper surface to establish line contact with the lower edge of the contact strip.

Now that the details of construction of the crank holder have been considered the next step is to point out how the frame is mounted for horizontal oscillating movement.

The section (Fig. 11) shows that a bolt 478 is passed horizontally through the vertical wall of frame bars 465 and 466 and each carries a roller 479. There are four such rollers 479 (Fig. 8), one at each corner of the crank holding frame. The two roller pivot bolts 478 on the right bar 465 are slightly longer than those on the other side, because they carry not only rollers 479 but also carry semi-circular keying blocks 480 (Fig. 11) which extend upward above the right hand rollers to key the crank frame to the large frame 365.

In Fig. 11, it is seen that four rails 482, 483, 484 and 485 are secured to, and extend inwardly from, the walls 410 and 411 of the large frame 365. It is between these rails that the rollers 479 oscillate horizontally to carry the crank holding frame back and forth. The two lower rails 482 and 484 are shouldered to confine the rollers laterally and there is a further guiding effect exercised by a long groove 486 (Fig. 11) cut into the underside of top rail 483 and into which the keying blocks 480 project.

Provisions are made to communicate the oscillating movement from the upper ends of two vertical arms to the two sides of the crank holding frames. Referring to the sectional plan view (Fig. 12), it is noted that bolted to the outside of both side bars 465 and 466 are extending yokes 488 and 489, the former being secured to the right hand angle bar 465 by bolts 490 and the other yoke 489 being secured to the left bar 466 by bolts 491. In the plan view (Fig. 8) it is seen that both the yokes 488 and 489 are shaped like a U with the arms extending outward from the crank holding frame. In the elevational view (Fig. 2), it is noted that the side arms of the yokes are flared outward in the lower portions 492, so that when the sensing unit frame is lowered the crank carriage tends to centralize itself over the rollers on the oscillating arms. Extending inwardly from the side arms of the yokes 488 and 489 are the heads of pairs of fiber buttons 493 (Fig. 8) provided to cooperate with both sides of the operating roller and to provide insulation for further separating the sensing frame electrically from the body of the machine. The buttons 493 on the yokes extend beyond the two main side frames, where they are available for engagement with the vertical operating arms which are about to be described.

The end sectional view (Fig. 10) shows that the large shaft 457 already mentioned as carrying the tube 456 extends through bearings in the two main side frames and at the right end carries a large vertical arm 495, the upper end of which carries a roller 496 (see also Figs. 5 and 8) in engagement with the yoke 488 extending from the right side of the crank holding frame. A similar arm 497 is fastened to the left end of shaft 457, and at its upper end it carries a roller 498 in engagement with the yoke 489 extending from the left side of the crank holding frame. A pair of shields 499 and 500 are fastened to the right and left walls, respectively, of the main sensing frame and extend downwardly to enclose the roller and yoke devices, so that they are shielded from the fingers of the machine operator.

The oscillating frame comprising shaft 457 and the two arms 495 and 497 are operated by the complementary cams 162 and 163 shown in the plan view (Fig. 3) and in Fig. 5 for cam 162 and previously mentioned as connected to the main driving gear 111. However, the camming action is not communicated directly to the oscillating frame but is connected through an adjustable operating lever variably set with relation to the right hand arm 495. This adjustable lever 502 (Fig. 5) is loosely pivoted on a hub extending from the arm 495 and is formed with a pair of arms, the upper arm carrying a roller 503 cooperating with the outer cam 162 and the lower arm carrying a roller 504 cooperating with the inner cam 163. The lever 502 is formed with a third extension formed with a slot 505 (Fig. 10) which is at an angle slightly off a radial line with respect to the center of shaft 457. Adjacent slot 505 there is a somewhat similar formation 506 in the arm 495, the difference being that the slot in arm 495 is also out of radial alignment and at a different direction than the direction of angularity of the slot 505. Extending through the two slots 505 and 506 is an adjustment and fastening bolt 507, the head of which is a flat rectangular extension 508 bridging across slot 505 and terminating in the end, which is slightly enlarged to pass through slot 506 and stop short of passage through slot 506, which is penetrated by a portion of the bolt 507 of a smaller circular area. Since the bolt 507 is adjustable vertically to extend through the two slots in any one of an infinite number of upper and lower positions, it will be realized that lever 502 is adjustable radially with respect to arm 495. When the proper adjustment is arrived at the nut on the outside of bolt 507 may be tightened to clamp it in the desired position along slot 506 and there it projects through slot 505 to hold the follower lever 502 in the proper relationship. As a further securing means a bolt 509 is threaded in lever 502 and passes through an arcuate slot 510 (Fig. 10) cut in a short lower extension of arm 495. Bolt 509 is loosened when adjustment is being made and then is tightened to clamp the arm lever together in cooperating relationship.

As a further means for adjusting the oscillating movement of the oscillating operator for the crank frame there is provided an adjustable clamping device between the two cams 162 and 163 and the gear 111, similar to the adjusting devices between levers 495 and 502.

In Fig. 3 it is seen that the two cams are connected by a hub 520 which is loosely mounted on the hub of the main driving gear 111 which is pinned directly to shaft 112. The cams are connected to gear 111 by an adjustment bolt 511

(Fig. 5) which passes through slots 515 and 516 cut in cam 162 and gear 111, respectively (see also Fig. 11). These slots 515 and 516 are not only of angularity differing from radial displacement but also different with respect to each other, so as to produce relative circular movement between the gear and cams when the bolt is shifted vertically. The bolt has an inner rectangular head 518 terminating a larger sectional area passing through slot 515 than the outer end area passing through slot 516. A washer is placed under head 518 and, when the nut is tightened, the gear and cams are fixed in the adjustable position. A further clamping action is exercised by a bolt 519 which passes through an arcuate slot in gear 111 and is threaded in cam 162 to tie the driving means together.

It will be noted that the bell crank sensing lever mechanism is independent of clutch operation and is operated invariably as long as the card feeding and sensing unit is being driven. Of course, there are other electrical controls for deciding when the impulses created by such oscillating movement of the levers are to be directed into the mechanism to be controlled. Therefore, even though the cranks operate continuously that is no indication that the contacts established thereby are effective to generate control impulses at all times.

The cams for oscillating the crank holding frame are proportioned to advance the seven rows of cranks 400 from left to right after the pins have dropped through perforations in the record. This movement is synchronized with accumulating or other accounting control devices and the impulses derived from the rocking movements of the cranks have value directly associated with the time of generation which in turn is controlled by the movement of cams 162 and 163. The timing of the cams and the generation of the impulses are brought out clearly with reference to the timing chart (Fig. 21a) which not only shows the relative position of each impulsive cycle but also the relationship between said impulses and the other operating controls for accumulating action.

The contact strips

It is noted with respect to Figs. 6, 7 and 11 that associated with each contact making crank 400 is a horizontal contact strip 407 which is poised above the button 404 on the end of the top arm of the crank to be contacted whenever the crank rocks counterclockwise, while passing over a depressed pin. Since there is such a strip 407 for each crank there are six rows of such strips with 60 strips in each row and two extra strips for the B deck rows having an extra sensing column position as already noted.

The sets of strips in the two different stations U and L are separated in two sets of three rows each with the related sets of three fastened to common insulation sheets 409 which are assembled in a compact formation as about to be described with reference to Fig. 7.

Two separate holders are provided, one to removably contain the contact strips 407 for station U, and the other for the strips at station L. Because they are identical in construction a description of one applies as well to the other. Although the holders are said to carry the contact strips 407, there is no metallic connection between any of the strips 407 and the holder, and really it is the insulation sheets 409 which are fastened in the holder to suspend the strips 407 separately

above the cranks 400. Each sheet 409 has fastened on one side by cycle welding or any space saving mode of connection a set of three contact strips 407, said strips being separated and having their lower edges projecting below the bottom edge of the sheet. Thus, the bottom straight horizontal edges of strips 407 are separately exposed and each is available for contact by a button 404 on the top of a crank 400.

Extending upwardly from strips 407 are the contact prongs 408 to receive and hold clips on the ends of separate wires leading to the plug-board of the machine. These prongs 408 are not only separated by the sheets 409 but they are also staggered in formation to allow more room for attaching and removing the top plugging clips.

Sheets 409 are formed with two end extensions 522 and 524 (Fig. 7) and the strips are located, supported and held by combs and bars co-operating with said extensions as about to be noted.

Fastened across the top of the main frame 395 (Figs. 6, 7, 8 and 10) by bolts 526 screwed in the side walls 410 and 411 is a pair of rectangular hollow frames 527 and 528, the former as the holder for the contact strips at station U and the latter being for the same purpose at station L. The walls of frame 527 are of an L-shaped cross section with the lower leg of the L facing outward at the sides (Fig. 11) and inward at the two ends (Fig. 7).

Fastened under the two ends by sets of four screws 529 (Fig. 7) are two comb bars 530 and 531 with teeth for separating the end extensions 522 and 524, respectively, of the insulation sheets 409. Attached under bars 530 and 531 are support bars 532 and 533, which extend to underlie the extensions 522 and 524 and confine them below the ledge of frame 527.

As a further locator and stiffener for the mid-section of the sheets 409 there is attached to ears 535 extending inwardly from frame 527, a comb bar 536 with downwardly pointing teeth 537 between which fit the upper edges of sheets 409 (see also Figs. 8 and 12).

It is noted from the foregoing that the insulation sheets 409 and the contact strips 407 thereon are held individually and fastened to hold them rigidly in place with respect to movement in all directions.

Since the stacker may be rocked away from the top of the sensing unit, the upper ends 408 of the contact strips 407 are readily available for the attachment of terminal plug wire connections and also for removal of the strips for inspection of the lower edges of the contact strips, whenever necessary. Because the entire sensing unit assembly is built on a unit basis, it is possible to separately remove and inspect the contact strips, the crank holder and the pin holder in the order mentioned.

The stacker mechanism

As a card leaves the second station L (Fig. 6) it passes out from between the two plates 316 and 425 and is guided upward beyond the last feed rollers by a slanted and upwardly curved guide plate 559, which is fastened between the side frames 26 and 27. The left curved end of guide 559 is curved to conform with the periphery of the stacker drum SD and by this means the card is advanced to the drum and partly around it.

It is noted hereinbefore that the stacker drum 75 gagement with the top of plate 73 serves to disen-

shaft 63 (Fig. 3) is driven by gearing including gears 126, 127, 129, 130, 131 and 134, so that the drum is turned clockwise a half revolution every time the rear gate clutch is tripped.

The stacker drum SD is made up of three sections, a right end section 560 (Fig. 9), a center joining section 561, and a left end section 562, all said sections being fastened together and on shaft 63.

Passing through the drum SD near the periphery and at 180° spacings are two sliding rods 563 in bearings in the wide walls of the end sections. These rods 563 carry four card clip frames 564, there being two such frames 564 spaced near the ends of the two rods, said frames projecting through four openings 565 in the drum to grasp the card.

Since all four clip frames 564 are similar in construction and operation a description of one applies to the other three. Each frame is of triangular shape with one corner 566 encircling the slide rod 563, the second corner being notched at 567 (Fig. 6) to slidably engage the drive shaft 63, and the third corner being formed as a pad 568 on which a card edge is held by the pinching action of a pair of thin curved blades 569 extending from a rockable arm 570 fastened to rod 563 between the two end arms 566 (Fig. 9) of the frame. An attached clamp 573 holds the blades 569 attached to arm 570 and extending rearwardly therefrom. A spring 574 tends to press the blades on pad 568 at all times. Each rod 563 is operated to rock and swing the tips of blades 569 against pad 568 with the front edge of the card between them. For this purpose, to the right end of rod 563 (Fig. 17) is attached an arm 571 bearing a stud on which is a roller 572.

The two rollers 572 are so supported by arms 571 that they project inwardly and ride around a pair of cam bushings 577 and 578 which are adjustably secured near the right end of shaft 63 just inside the frame member 65 upon which the swinging stacker frame is secured. These cams 577 and 578 are shaped to hold the rods 563 in such a position as to rock arms 571 so that the spring blades 569 extending from the arm 570 thereon normally grasps or pinches the record card to the drum. However, there are two positions wherein two high points on the cam surface rock the arms 571 and rods 563 in a clockwise direction (Fig. 6) to open a space between blades 569 and pad 568. One of the two positions wherein the parts are separated for allowing the card edge to project therebetween is shown in Fig. 6 and it is in this position that a card coming out of the last sensing station L is projected beyond guide 559 and into the position wherein blades 569 are allowed to swing counterclockwise as urged by spring 574 so as to engage the card between blades and the pad 568. Since there are two arms 571 on each rod 563 and said arms each containing two blades 569, it is evident that the card is clamped to the stacker drum by four of the blades and is carried thereby in this position which is maintained for more than 180° as the stacker drum rotates in a clockwise direction to bring the card over to the almost vertical position in front of the retaining frame 71. At the stacking position the bottom plate 73 of the card holder projects into the annular opening 579 in the central section 561, and is, therefore, in the path of the leading edge of the card as it is being pulled around on the stacker, and en-

gagement with the top of plate 73 serves to disen-

gage the card from the stacker and deposit it in the hopper frame.

The accumulator

In Fig. 18 the driving shaft 713 is suitably geared to the card feed rollers so as to make one revolution for each cycle of operation. For each denominational order of the accumulator this shaft 713 has a gear 714 secured thereto which drives the adding clutch mechanism. The accumulator and clutch driving mechanism is of the same construction as shown in Lake et al., Patent 2,328,653 and Daly, No. 2,377,762 and includes a ratchet 715 which is free on post 716 and integral with a gear 717 driven by gear 714 (Fig. 19). Rotatably carried by post 716 is a disk 720 having ten teeth 720a adapted to be engaged by a tooth 721a on the long arm of a clutch lever 721 to hold the disk against rotation in a counterclockwise direction.

At the side of disk 720 is a register or adding wheel 724 rotatable on post 716 and provided with ten peripheral notches 724a. Wheel 724 may take any of ten rotative positions with the values 0, 1 . . . 9. A spring-pressed lever 725 engages with a notch 724a of wheel 724 to hold the wheel impositively and to center it in the value position into which it has been rotated. A transfer cam 726 is fixed to the side of wheel 724 and a stud 727 in wheel 724 extends through an opening in disk 720 to pivotally carry a clutch dog 730. A spring 731 urges the tooth of dog 730 to engage ratchet 715. In the position shown in Fig. 18 the clutch lever 721 is in declutching position, its tooth 721 is restraining rotation of disk 720 counterclockwise and dog 730 is clear of ratchet 715. The dog 730 is being held clear of the ratchet by coaction of a pin 730b on the dog with a cam edge 720b of disk 720.

When the clutch lever 721 is dropped to cause its tooth 721a to release the disk 720 for counterclockwise movement, the spring 731 is effective to rock the dog 730 into engagement with ratchet 715. During this movement of the dog 730 its pin 730b rides along the cam edge 720b and cams the disk counterclockwise until its tooth 720a previously engaged by tooth 721a is to the right of the latter tooth. The parts are then in the clutching position shown in Fig. 17, and the register wheel 724 is coupled to the driving device 715, 717 for rotation. Through engagement of the pin 730b of the dog 730 with cam edge 720b, the disk 720 is forced to rotate counterclockwise together with the register wheel.

When the clutch lever 721 is returned to upper declutching position, its tooth 721a intercepts a tooth 720a of disk 720 and stops the disk. Register wheel 724 and dog 730 continue rotating while cam edge 720b of disk 720 cams the pin 730b outwardly until it is again in its outer position. As the pin 730b is cammed outwardly clutch dog 730 moves clear of ratchet 715 and declutches the register wheel from the driving means. The register wheel is then held and centered in its new value position by lever 725. A spring-urged latch 735 serves to hold lever 721 in either clutching or declutching position.

The clutch lever 721 has a short arm swiveled to the lower end of an armature 736 which is disposed between an advance magnet AM and a stop magnet SM. Energization of magnet AM rocks armature 736 clockwise to lower lever 721, and energization of magnet SM rocks armature 736 counterclockwise to raise the lever 721.

When the wheel 724 is in its 0, 1 . . . 8 positions,

the cam 726 holds a carry lever 737 pivoted at 738 in the position shown in Fig. 18, where a contact blade 739 (insulated from lever 737) takes a midposition between contact elements 740 and 741. When the wheel is in its 9 position a tooth on lever 737 is dropped into a cut 726a of cam 726 and blade 739 contacts element 741. When the wheel 724 passes from the 9 to 0 position a rise 726b rocks lever 737 to cause blade 739 to engage element 740. When the lever is so rocked an arm 742 integral therewith is engaged and held by a spring-urged latch 743 which maintains the contact engagement between 739 and 740 until a pin 744 in gear 714 strikes an arm 745 integral with the latch 743 to release lever 742. The point in the cycle at which such unlatching occurs is indicated in the time chart. The accumulator is also provided with a mechanical knockoff or declutching mechanism which comprises three pins 751, 752 and 753 secured to the side of gear 714 and adapted during rotation of gear 714 to ride in succession under an edge of clutch lever 721.

Assume the clutch lever to be in lower position, when either pin 751, 752 or 753 engages lever 721, it cams it upwardly into the position of Fig. 18. The knockoff pins 751, 752 and 753 are effective at fixed points of the cycle as indicated in the timing diagram of Fig. 21a.

Total readout

The accumulator shown herein is provided with an electrical total readout which may be of the form shown and described in the patents to C. D. Lake et al., No. 2,232,006 and No. 2,138,636 and G. F. Daly, No. 2,377,762. Since the construction of the electrical total readout is well known in the art it is only shown diagrammatically in the wiring diagram of Figs. 20d and 20e. As shown therein rotatable with an accumulator wheel of each order is a brush 663 which makes contact with a common segment 662 and with one or another of the digit segments 661 according to the digit representation of the accumulator order. The same digit segments 661 are interconnected by wires 664, or they may be strips also engaged by brushes 663. The digit segments receive digit impulses 5, 3, 1, 0 transmitted by cam contacts CR97-CR106 and according to the digit positions of each readout order, selected impulses 5, 3, 1, 0 are transmitted to a combinational code translator, and converted thereby to a decimal digit equivalent to select the digits to be printed.

Translator and total digit printing mechanism

The present machine is provided with a printing mechanism which is adapted to print items and as shown herein to also print the totals entered in an accumulator. As will be clearer later on the accumulators values are not read out from the readout as decimal representations but by combinational coded representations which are translated to the decimal equivalents by a translator which will now be described.

Reference character 822 (Fig. 22b, Fig. 23) represents a shaft which is rotated one revolution for each machine cycle. The shaft 109 which drives the card feed mechanism is driven by shaft 822, and interposed between shaft 109 and shaft 822 is the card feed clutch which is engaged by the energization of the CF clutch magnet (Fig. 20a). The card feed clutch is well known and CF magnet corresponds to card feed clutch magnet 48 of Fig. 6 of Patent No. 2,042,324.

There will now be described the translating or converting mechanism which converts the combinational digit representations transmitted under control of the readout to a decimal equivalent which is necessary to select digit type to print the digits of the total.

Cams 800A, 800B, 800C and 800D (Fig. 22b) are driven by driving means to be subsequently described one revolution for each cycle of operation of the machine. It will be noted that these cams differ in their cam contours and the particular cam portion which is effective in each point of the operating cycle is shown in the timing diagram of Fig. 21b. Each of the cams is provided with cam heights which are identified by three dotted circles associated with the cam 800A, which circles are of three different diameters and represent the heights of the cam contours as Low, Medium and High. The corresponding designation is shown in the timing diagram of Fig. 21b for such cams to identify the particular cam portion effective in each point of the operating cycle. The cams 800A, 800B, 800C and 800D may for convenience in construction be extended longitudinally to provide fluted cam rods having the configuration and outline in Figs. 22a, 22b to cooperate with a plurality of orders.

Each cam 800 cooperates with a related releasing and blocking member 810. The reason that the member 810 is called a releasing member is that when elevated a predetermined distance by the Medium or High cam portion of the related cam 800 it will release the operating link 863 for movement but when in its normal lower position (due to the Low cam portion) it will block the link 863 against movement. Each member 810 is slidably mounted in a slot 801 of a guide block 802 and is further guided by a rod 804 which receives a guide slot 803 of the related member 810. Also pivoted on a rod 805 carried by the block 802 is a latch pawl 806. Interposed between the pawl 806 and the associated member 810 is a compression spring 807, the spring 807 functioning to urge the member 810 downwardly so as to always press against and contact with the cam contour of the related cam 800. Each member 810 is provided with a shoulder 808 cooperating with a lug 809 formed as an integral part of the link 863.

The link 863, referring to Fig. 22a, is slidably mounted in guide slots formed in a support plate 811 to support the link 863 at one end and guide its movement, and referring to Fig. 22b the other end of the link 863 is dependently hung by arm 813, which arm has a cam follower extension 818. A compression spring 814 fitting in a spring support and guide block for arm 813 urges the link 863 to the left and when such spring is effective for action under control of a cam 825 it serves as a source of mechanical impulse transmitted to link 863 at a differential time to rock a clutch release arm 867 to engage a clutch to initiate rotation of a type wheel.

Recalling now that each cam 800 has cam contours of three different heights, it should be observed that when member 810 is at a position determined by the low portion of the cam 800 the shoulder 808 abuts lug 809 to block the link 863 from movement to the left, urged by compression of the spring 814. In attempting to do so lug 809 will bear against the shoulder 808 and urge the member 810 clockwise, which movement is restrained by the cooperation of an upstanding hooked portion 812 of member 810 against the

latching end of the pawl 806. Assuming now that a cam has been rotated so that the Medium cam portion of the cam contour has raised the member 810, such difference in cam height with respect to the Low cam height will elevate shoulder 808 slightly further above the related lug 809 and by the continued cooperation of the hooked extension 812 of the member 810 with the extremity of the pawl 806, clockwise movement of the pawl 810 will still be restrained.

Assuming now that the High cam portion has positioned the member 810 to its maximum height, the shoulder 808 will be still further above the lug 809 and the member 810 is now in such position that the compression spring 807 will be effective to rock the member 810 clockwise so that a hooked extension 812 will catch over the latch end of pawl 806, provided that at this time the pawl 806 is rocked counterclockwise due to the transmission of an impulse to magnet 861 at the time the member 810 is in its highest position. If the pawl 806 is not rocked slightly counterclockwise, no latching of the member 810 will take place. Summarizing, whenever the High portion of a cam has elevated a member 810 to the highest position such member will be latched if the related pawl 806 is concurrently rocked to latching position. If there is no rocking of the pawl 806 at this time member 810 will not be latched, and will be subsequently free to move up and down in accordance with the successive cam contour as the related cam 800 rotates.

The above description has been confined to the operation of the parts under control of the cam 800A but it should be noted that identical operations are effected under control of the remaining cams 800B, 800C and 800D. For this reason, the description of operation need not be repeated for duplicate parts.

For the purpose of rocking the pawls 806 to latch those members 810 which are at their highest position it will be seen that referring to Fig. 22b each translator control magnet 861 when energized attracts an armature 815 and rocks the same so as to shift a related connected link 816 to the left. Extending from the link 816 are four integral extensions 817, each of which cooperates with the related pawl 806. The result of this construction is that the impulse directed to the magnet 861 will shift the link 816 and rock the four pawls 806 concurrently but only that pawl 806 is effective for latching the related member 810 if the associated member 810 has been elevated to its highest position. Therefore, one or more of the pawls 806 may be rocked idly at the same time without latching the related members 810.

To prevent the armature 815 from sticking to the core of the magnet 861 due to residual magnetism, it is desirable to provide means to positively restore the link 816 and armature 815 to normal by mechanical means timed with the rotation of the cams 800. To this end there is provided a magnet knockoff cam 820 (Fig. 22a) notched as shown. A follower arm 821 of a clutch release arm 824 cooperating with the cam 820 has a depending arm 822 urged by a spring 823 against an upstanding finger of the link 816. At the time the magnet 861 is energized it will be observed that follower arm 821 cooperates with a notch 820a of the cam 820. Thereafter, such arm cooperates with the following cam portion 820b to rock arm 821, link 816 and armature 815, restoring the armature 815 to normal if it should

remain attracted to the core under the above circumstances.

Referring now to Fig. 21b, it is obvious that at the time the impulses 5, 3, 1, 0 are directed by cam contacts to be described to magnets 861, one of the cams 800 will have its High portion in cooperation with the latching members 810. For example, at the time the 5 impulse is directed the High portion of cam 800A will be effective. At the time the 3 impulse is directed only cam 800B will have a High portion effective at this time. For all of the electrical impulses 5, 3, 1, 0, this condition may be represented by the following table:

Impulses	Members 810 latched
5	810A
3	810B
1	810C
0	810D

It is obvious from the above table that members 810 are latched singly or in predetermined combinations, according to the code so that at the termination of the transmission of the electrical impulses 5, 3, 1, 0 all or some of the members 810 will be latched, and others will not be latched and therefore free to be positioned according to the contour of their cams during their subsequent rotation. It is explained that once a member 810 is latched it is not free to thereafter move upwardly and downwardly in accordance with the subsequent cam contour of the related cam, but remaining unlatched members 810 can do so.

Movement of the operating link 863 to the left during the time that the 5, 3, 1, 0 impulses are transmitted, which movement might be permitted if all of the four members 810 for this order may be either latched or elevated so as to be above the lugs 809, is restrained by a cam portion 825a of cam 825 (Fig. 22b). This cam, through driving means to be subsequently explained, is driven synchronously with the cams 800 and 820 and cooperates with the follower extension 818 of arm 813. As shown in the timing diagram, during the transmission of 5, 3, 1, 0 impulses, the High portion 825a of cam 825 will restrain movement of the operating link 863 to the left.

After latching of members 810 in predetermined combinations the contour of the cams 800A, 800B, 800C and 800D which are thereafter effective will determine the time in the operating cycle that the operating link 863 will be moved to the left in a manner now to be described in detail.

After one or more members 810 are latched in combination according to the impulses transmitted as indicated in the preceding table, the further rotations of the cams 800A, 800B, 800C, 800D will raise and lower the remaining unlatched members 810 according to the cam contours of the respective cams, but during said further rotation of the cams the link 863 will be restrained against movement by one or more of such unlatched members until a point is reached in the operating cycle when the cams related to the unlatched members concurrently present cam operations of Medium height to the unlatched members. It will be recalled that since the latched members 810 are so positioned that they do not restrain the movement of the link 863 under the influence of the spring 814 and further the elevation of any unlatched member by a cam portion of Medium height will also unlock the link 863, it is obvious that when both of these condi-

tions exist for four of the members 810, the link 863 is then free to move under the influence of the spring 814 and cam 825. This will be made clear by reference to a particular example.

If, for example, the 5, 3, 0 impulses (representing 9) are transmitted under control of a readout order when it represents 9 members 810A, 810B and 810D are latched due to the High cam portions of their respective cams 800A, 800B and 800D and such latching of members 810A, 810B and 810D is completed about 75° of the operating cycle (see Fig. 21b). At this time, the members 810A, 810B and 810D are latched in the highest position so that they unlock the operating link 863 at such positions. However, cam 800C in its subsequent rotation continues to lower and raise the related unlatched member 810C and such unlatched member 810C will restrain the operating link 863 from movement until about 123° of the operating cycle, at which time cam 800C through its Medium high cam portion shifts related latching members 810 to unlock the link 863. At this time cam follower extension 818 of the arm 813 will cooperate with the notch 825b designated 5, 3, 0 in both Fig. 22b and the timing diagram of Fig. 21b. Operating link 863 is now unlocked at four points and the movement of the link to the left is effected at about 123° by spring 814. The link will now operate the clutch release arm 867 and therefore engage a type selecting clutch to be described to initiate the rotation of the printing wheel 809 to select the numeral type 9.

Reverting now to Fig. 22b, when the operating link 863 is moved to the left to effect the engagement of the type selecting clutch the cam follower extension 818 is in the bottom of the notch 825b of the cam disk 825 and further rotation of the cam 825 in a clockwise direction will, through the following inclined cam portion 825c, cooperate with the cam follower extension 818 to positively restore the operating link 863 to the right without, however, causing the unlatching of any latched member 810. At about 315° an extra High cam portion 825d will shift link 863 to the right beyond the normal position, and in so doing for those members 810 which have been latched lug 809 will engage the shoulder 823 of the respective member 810 to rock the same counterclockwise to unlatching position, spring 807 being compressed during this operation to rock pawl 806 to normal position. With respect to any unlatched member 810, movement of the link 863 to the right at this time may also effect movement of such members 810 but the operation of such is ineffective.

While the operation of the machine has been described in connection with the manner of engaging the type wheel clutch when the 5, 3, 0 impulses are transmitted, to select the 9 type when a readout order represents 9, the same principle of operation for effecting the above results is involved for other combinations of impulses as is evident from the following table:

Readout Digit Representation	Impulses Transmitted	Members 810 Latched	Cams 800 at MEDIUM Cam Portion
9	5, 3, 0	810A, 810B, 810D	800C
8	5, 3	810A, 810B	800C, 800D
7	5, 1, 0	810A, 810C, 810D	800B
6	5, 1	810A, 810C	800B, 800D
5	5, 0	810A, 810D	800B, 800C
4	3, 0	810B, 810D	800A, 800C
3	3	810B	800A, 800C, 800D
2	1, 0	810C, 810D	800A, 800B
1	1	810C	800A, 800B, 800D
0	0	810D	800B

It will be recognized from this table that the concurrent position of cams 880 at a medium height cam portion for those cams which have not previously latched members 810 will determine the time the mechanical impulse is transmitted.

The mechanical impulse transmitted to link 863 causes the engagement of a clutch to rotate a printing wheel 860 to a selected digit position.

When the clutch is engaged it is driven by a shaft 839, rotated by means to be later described.

For each printing order there is pivoted on a rod 866 a triple arm member consisting of arms 864, 865 and a clutch release arm 867.

Shaft 839 has secured thereto a tube 868 which is fluted transversely along its periphery to provide clutch notches 869. Tube 868 constitutes the driving clutch member. Encircling the clutch tube 868 is a plurality of gears 870, there being one gear for each order of the printing mechanism. For mounting the gears 870 on the clutch tube 868 each gear has integral therewith a flange 872. To provide for the lateral spacing between the gears 870 the gears are guided by guide slots 871 formed in guide blocks 873 and 874. By such spacing members the gears 870 are separated to allow independent rotation and to also locate a clutch pawl 876 which is pivoted on the related gear to cooperate with the clutch release arm 867. The clutch release arm 867 normally holds the clutch pawl 876 in such position that its tooth 877 is out of engagement with any of the clutch notches 869 of the clutch tube 868. When the clutch release arm 867 is rocked as a result of the actuation of the operating link 863 at a differential time, the clutch is engaged because a spring 878 attached to clutch pawl 876 will rock the latter in order that the clutch tooth 877 will engage a clutch notch 869 determined by the differential time the operating link 863 is actuated. The above described clutch is the printing type selecting clutch and causes the differential rotation of the printing wheel 860, since the gear 870 and the printing teeth of the type carrying wheel 860 are intergeared.

Figs. 22a and 22b show the arrangement of the total digit printing devices for a single order and the machine is preferably provided with duplicate devices for printing a plurality of digits of the total.

If, as previously described, the operating link 863 was shifted at about 123° as a result of the 5, 3, 0 digit impulses because a readout order represents 9, the clutch release arm 867 would be rocked at this time and pawl 876 would be released and rocked by spring 878 so that clutch tooth 877 engages a clutch notch 869, and printing wheel 860 will thereafter continue to rotate to such position as to present the numeral "9" to the printing line. The differential time at which the operating link 863 is actuated determines the extent of counterclockwise rotation of the printing wheel 860 from a rest position necessary to select a numeral type. After the predetermined extent of rotation of the printing wheel 860 has been effected and the printing impression has been effected, with the type selecting clutch still engaged, the printing wheel 860 will continue to rotate until the free end of the clutch pawl 876 strikes the clutch release arm 867 which, in the meantime, has been brought to its normal position, by means of a compression spring 879 (Fig. 22a). When such disengagement is effected the printing wheel 860 is at the normal position shown in Fig. 22a.

Each printing wheel 860 is carried by an arm 75

881 loosely pivoted upon a rod 882 and provided with a rearwardly extending follower extension 884 which is operated by a cam projection 883 of a cam disk 885 which constitutes a driven member of a printing clutch.

Shaft 838 rotates a clutch tube 886 fixed thereto and likewise encircling the clutch tube 886 is the driven clutch disk 885 upon which is pivotally mounted a clutch pawl 887. Clutch disk 885 and parts carried thereby are guided similarly to gear 870. Associated with the clutch pawl 887 is a clutch release arm 888. When the clutch engagement is effected between the clutch pawl 887 and one of the clutch notches of the clutch tube 886, the disk 885 will be rotated in a clockwise direction, whereby the cam projection 883 will cooperate with the follower extension 884 to rock arm 881 about the rod 882 against the action of the return spring 889. The engagement of the clutch now being described is effected when the printing control magnet 861 for each order is again energized for numeral printing by an "N" impulse.

When the printing clutch engagement has been effected, each cam 885 will cooperate with the related follower extension 884 to rock the associated printing arm 881 to force the printing wheel 860 against the usual inking ribbon and platen 890 around which platen is positioned the paper strip to be imprinted. As each arm 881 is rocked against the action of the spring 889, the printing wheel 860 is being rotated counterclockwise but since the printing wheel is now rolling over the gear 870 this rolling action will cause an equal and simultaneous rotation in a clockwise direction. Both of these opposite rotations will, in effect, cause the printing wheel to be substantially immobile with respect to its rotation when it moves to the right to strike the platen 890, the type striking the platen squarely and firmly to cause a legible impression.

After the printing operation, when cam extension 883 of the cam disk 885 passes by the follower extension 884, spring 889 will not be effective to return the type wheel carrying arm 881 to normal position and the extension 884 now bears against the circular peripheral edge of the cam disk 885.

After the printing operation, since the type selecting clutch is still engaged, the printing wheel 860 continues to rotate as previously stated until the clutch pawl 876 strikes the clutch release arm 867 which, in the meantime, has been positioned to normal, thereby disengaging the type selecting clutch when the printing wheels are at normal position.

The printing clutch continues its engagement for a complete rotation of the cam 885 and the clutch disengagement is effected by the engagement of the clutch pawl 887 with the clutch release arm 888.

As the free end of the clutch pawl 876 strikes the clutch arm 867 there is a tendency to cause the gear 870 to rebound counterclockwise. This action is prevented by the cooperation of a spring-pressed detent 896 with a shoulder 897 of a plate 898 secured to each gear 870. When the normal position of the clutch is obtained, the detent 896 will engage the shoulder 897 to prevent such rebound and retain the clutch parts in their normal position.

A somewhat similar rebound preventing mechanism is also provided for the printing clutch which consists of a spring-pressed detent 891 cooperating with the shoulder 899 of the cam disk

Upon the transmission of said "N" impulse, by a circuit to be described, the second energization of the magnet 861 again attracts its armature 815 and shifts link 816. The latter thereupon rocks clutch release arm 824 to unlatch the clutch release arm 888 of the printing clutch. At this time a low portion 820c (see Fig. 22a) of a cam 820 cooperates with the cam follower extension 821 so as not to restrain the rocking of clutch release arm 824. When the clutch release arm 888 is unlatched a depending extension 827 moves in a clearance portion 826 of said arm 824. Cam disk 885 will now rotate counterclockwise and the cam extension 883 will strike the follower extension 884 at the time the selected numeral type is at the printing line to effect the printing impression.

It is undesirable to have the clutch release arm 888 released whenever link 816 is rocked the first time to rock arm 824 to engage the printing wheel clutch and during this time a high portion 837a of cam 837 cooperates with arm 888 to block it against movement to release the printing clutch. When the N pulse is transmitted as will be later described the low portion of cam 837b will cooperate with clutch release arm 888 to permit its rocking to engage the printing clutch. After this the cam rise 837c of cam 837 will function to positively retract the clutch release arm 888 to normal position to cause disengagement of the clutch release pawl 887 after a complete revolution of the printing clutch. At the termination of the operating cycle a cam rise 820d of cam 820 functions to rock the clutch release arm 824 clockwise to again position it beneath the extension 827 of the clutch release arm 888, which previously has been elevated to the position shown in Fig. 22a. The cam rise 820d also shifts link 816 to restore armature 815 to normal if it should stick to the core of magnet 861.

Gear drive for printer

In Fig. 23 reference numeral 838 designates the printing impression drive shaft which is driven at a uniform speed of rotations for each cycle of the operation of the machine. The drive shaft 822 has secured thereto a gear 940 which drives a gear 941 secured to the printing impression drive shaft 838 to rotate the latter at a uniform speed of rotation of one and a half revolutions for each revolution of drive shaft 822.

Shaft 839 represents the type selecting drive shaft which rotates 2½ revolutions for each operating cycle. The shaft 839 is driven at times with a uniform speed of rotation synchronous with the drive shaft, but at other times the speed of rotation given to shaft 839 is decreased or increased with respect to drive shaft 838, in order to select the desired alphabet type of a selected group of alphabet type. This means to effect the variable drive of shaft 839 is disclosed in full details in Patent No. 2,439,445, issued to H. S. Beatie, and since the alphabet printing is of no concern here it need not be described to understand the present invention. With such variable speed drive the shaft 839 will rotate the type wheel at a decreased speed to present the selected numeral type to the platen at about 330° of the cycle, at which time the previously clutched printing cam 885 will have its cam projection 883 in position to strike the projection 884 to impress the selected numeral type against the platen 890.

The machine includes a driving means driven by the shaft 822 for rotating the cams 800A, 800B, 800C and 800D, 820, 825, 837 and 887 in

synchronous relationship and such cams are driven one complete revolution for each operating cycle.

The driving means for driving cams 800A, 800B, 800C and 800D will now be described. Secured to shaft 822 is a gear 1040 (Fig. 23) which, through a gear 1041, drives a gear 1042 secured to the drive shaft 1043 for the cam 800D. Shaft 822 is extended to directly drive the cam 800C. Referring to Fig. 23, gear 1040 through a gear 1044 drives a gear 1045 secured to the drive shaft 1046 for cam 800B. Gear 1045, through an idler gear 1047, drives a gear 1048 secured to the drive shaft 1049 for the cam 800A. By such driving means the cams 800A, 800B, 800C and 800D are driven synchronously.

Referring to Fig. 23 gear 1044 has rotatable therewith a gear 1050 which, through an idler gear 1051, drives a gear 1052 attached to the shaft 1053 to which the cam 825 is secured.

Gear 1050 also meshes with a gear 1054 secured to a shaft 1055 to which shaft the cam 820 is secured.

Also referring to Fig. 23 to drive shaft 838 there is secured a gear 1056 which meshes with a larger gear 1057 secured to a shaft 858 to which shaft the cam 837 is secured.

Thus, through the intergearing last described, the operating cams 820, 825 and 837 are driven synchronously with the operating cams 800A, 800B, 800C and 800D.

Wiring diagram

Reference characters 615 and 616 represent in Figs. 20a-20e the main power lines to which current is supplied when the main line switch is closed.

Card feed control circuits

40 After the main switch has been closed, the depression of a start key and closure of its contacts 617 (Fig. 20a) serve to energize the pickup coil of a start relay R12 when CR6 cam contacts close, as follows: Line 615, cam contacts CR6, wire 45 618, key operated contacts 617, pickup coil of R12, wire 619, to line 616. Relay R12 establishes a holding circuit for itself through cam contacts CR5, wire 620, holding contacts R12a, holding coil R12H, wire 619 to line 616.

50 Other contacts R12b of start relay R12 are closed to prepare an automatic start circuit through relays R13 and R14 to be independent of the start key and dependent on the presence of cards in the magazine and a certain condition in 55 the card stacker. The initiating circuit for relay R13 includes line 615, wire 623, stop key contacts 624, wire 625, error relay contacts RE2 now closed, contacts R12b, relay R13, wire 619 to line 616. The hold circuit for R13H is from line 615, CR4 60 cam contacts, R13b contacts, R13H coil, wire 619, line 616.

Relay R13 closes contacts R13a in series with the pickup coil of the automatic start relay R14. The pickup circuit is from line 615, cam contacts 65 CR3, wire 628, contacts R13a, MT2 contacts now closed, pickup coil R14, wire 619 to line 616. Relay R14 then closes contacts R14a to set up a holding circuit from line 615, cam contacts CR2, wire 629, contacts R14a, the holding coil R14H, wire 70 619 to line 616.

Associated with relay R14 are contacts R14b for closing the pickup circuits of all clutch control magnets of the card feed unit including the front gate control which is the card feed and picker operating magnet FG. Operation of this

last mentioned clutch magnet serves to initiate card feeding by means of the circuit from line 615, wire 630, relay contacts R14b, wire 631, cam contacts CR125, wire 632, clutch magnet FG, wire 633, to line 616. Operation of the picker serves to advance the first card into the first sensing station U, and in so doing it operates the card lever 298 to close contacts 252 and energize a relay R4 to effect one of the sustaining controls associated with the card sensing unit.

The pickup circuit is from line 615, cam contacts PC2, card lever contacts 252, the pickup coil of relay R4, wire 619 to line 616. A holding circuit is established for the holding coil of relay R4 by the closure of associated contacts R4a by a circuit from line 615, cam contacts PC1, relay contacts R4a, the holding coil of relay R4, wire 619 to line 616.

Another of the sustaining conditions is based upon the presence of the record cards in the magazine as evidenced by the closure of the usual hopper contacts 296 closed in a well known way and the energization of a hopper control relay R1. The circuit for the hopper relay R1 is from line 615, contacts 296, relay R1, wire 619 to line 616. Relay R1 then closes associated holding contacts R1a to establish a holding circuit from line 615, cam contacts PC3, relay contacts R1a, relay R1, wire 619 to line 616.

In addition to the indication that a card is passing into the first sensing station, it is required that a later indication be given to sustain the control exercised by the same card as it passes the second sensing station. This function is performed by relay R7 which is picked up through the R4 holding circuit and sustained for an additional cycle. The pickup circuit for relay R7 is from line 615, cam contacts PC1, relay contacts R4a, cam contacts CF3, the pickup coil of relay R7, wire 619 to line 616. The holding circuit for relay R7 is established by closure of related contacts R7a and the additional closure of cam operated contacts 581 closed near the end of the cycle whenever the stacker is in operation. This closure is effected by cam closing means not involved in this invention but fully disclosed in the application, Serial No. 768,639, filed August 14, 1947. The holding circuit for relay R7 is from line 615, hopper contacts 581, relay contacts R7a, the holding coil relay R7, wire 619 to line 616.

Now that it has been pointed out how the relays R1, R4 and R7 are energized, depending on the presence and advancement of record cards, further illustration of the controls over starting and sustaining the record feed may be explained.

In connection with the maintenance of energization of start relay R13, it will be noted that the energization of R13 relay is made independent of start key depression after the first cycle for advancing the record. This is done by means of contacts R1b, R4b and R7b, all arranged in series with each other and with relay contacts R13b to sustain R13 energized as long as cards are present. The complete supplemental holding circuit is from line 615, wire 623, stop key contacts 624, RE2 relay contacts now closed, relay contacts R1b, R4b and R7b, relay contacts R13b, relay R13H, wire 619 to line 616. By means of the sustained energization of relay R13, it is possible also that relay R14 be maintained through the closure of contacts R13a, and the condition is maintained by the presence of the records in the magazine and their advancement through the sensing unit.

It is already noted that the clutch magnet FG

for the first card feed control gate and the picker mechanism is operated through cam contacts CR125 and the automatic start control relay contacts R14b. Along with such energization there is an early operation of the first pin holder shifting clutch control magnet FP which serves to lower the pins into cooperation with the record at the first sensing station U. The circuit through clutch magnet FP is dependent upon the closure of relay contacts R4c which, it will be remembered, become effective by action of the card lever 298 showing that a card is entering the first station.

Also dependent upon the action of the relay 15 R4 is the energization of the main card feed clutch control magnet CF to connect a shaft of cams to the main drive. For this purpose a relay contact R4d is in series with clutch magnet CF. The circuit is from line 615, wire 630, start control 20 contacts R14b, wire 631, cam contacts CR126, relay contacts R4d, card feed clutch control magnet CF, to line 616. The foregoing circuit refers to the magnet CF which is used to clutch the main drive shaft to the drive shaft of the card feed 25 unit and cause rotation of the shaft for operating the CF cam contacts. The CF contacts operated by rotation of the shaft rotated by the CF clutch magnet are differentiated from the constantly running cam contacts CR, since the latter have a direct connection with the main driving shaft.

The record is released from the second sensing station by the action of the rear gate clutch magnet RG which is under the joint influence of 35 the hopper controlled relay R1 and the first station card lever relay R4. Normally, the circuit for the rear gate operation is controlled by contacts R4c and the complete circuit is as follows: From line 615, through wire 630, automatic start 40 contacts R14b, wire 631, cam contacts CR125, relay contacts R4e, wire 642, clutch magnet RG, wire 633, to line 616. When the last card of a stack is to be passed out of the second sensing station, there is lack of control by relay R4 and then the circuit is directed through a pair of 45 normally closed hopper control relay contacts R1c. These contacts are arranged in shunt around relay contacts R4e and take over the circuit connections normally directed thereto and serve to hold the clutch magnet RG energized for the last card feeding cycle, after which the start control contacts R14b open to terminate all card unit clutch controlled operations.

Along with the control of the record after it 55 passes into the second sensing station, it is desired to energize the pin holder clutch magnet RP relating to the pin sensing devices in the rear station L. Energization of this magnet is dependent upon joint operation of the first station card lever relay R4 and second station card lever relay R7. The complete circuit is as follows: Line 615, wire 630, automatic start contacts R14b, wire 631, cam contacts CR125, relay contacts R4e, 60 relay contacts R7c, clutch control magnet RP, wire 633, to line 616.

Automatic group control circuit

The automatic group control device is a well known feature in record controlled accounting machines and is utilized herein to initiate total taking and reset operations. Also, as is well known, several columns comprising a field of the record card are allocated to represent the group numbers. In the present embodiment only three

orders or columns of the group control circuit are shown for simplicity, and of these only the plug connections for one order for control at the upper reading station and one at the lower reading station, are shown in Fig. 20b. From the plug socket 651 of the hundreds order of the column allocated for group control at the lower reading station there is a plug connection 652 to plug socket 653 which is connected to the pickup coil of RC1. Correspondingly, there is a plug connection 654 for the hundreds order at the upper reading station to pick up the RC2 control relay. RC1 and RC2 relays thus receive electrical impulses 5, 3, 1, 0 according to the combinational hole representation in the corresponding columns of the card at the lower station and at the upper station. The impulse circuit is the same for each station and is traced for the lower station being from line 615, cam contacts CR34 which transmits impulses at the times the 5, 3, 1, 0 holes are sensed, wire 655, contact bar 395, contact bell crank 400, contact strip 407, plug socket 651, plug connection 652, plug socket 653, RC1 pickup coil, to line side 615. Thus, RC1 is energized by electrical impulses, and at the same time the RC2 is energized by corresponding electrical impulses, if the digit representations are alike. Each pickup coil RC1 or RC2 is held energized by a hold circuit extending from line 615, cam contacts CR34, wire 655, RC1a, or RC2a hold contacts, hold coil H of RC1 or RC2, to line 616.

The comparing circuit involves the b contacts of the RC1 and RC2 relays of the same order, and such transfer contacts are so interconnected in a circuit network that if RC1 and RC2 relays of the same order are concurrently energized the "b" contacts transfer concurrently and thus keep the circuit between wire 656 and a plug socket 657 open. However, a dissimilarity in card holes in the compared card columns results in the transfer of one of the "b" transfer contacts alone and thus a circuit will be completed from line 615, CR34 cam contacts, wire 655, wire 656, RC1b now transferred, by way of example, RC2b now normal, plug socket 657. When three orders are used for common control jumper plug connections 658 are made and thus unlike card holes in any column will close the circuit and by a plug connection 659 pick up the pickup coil of the M11 control relay, which latter has a wire connection 660 to the line side 616.

Minor total taking operations

As is well known in tabulating machines, there may be an automatic control by several control sections such as minor, intermediate and major, but for simplicity only the control by the minor section is shown and explained herein for the purpose of taking a total accompanied by a reset of that accumulator.

When the pickup coil of M11 is energized, as has just been described, it closes its M11-1 hold contacts providing a hold circuit from line side 616, wire 660, M11H relay coil, M11-1 relay contacts, CR41 cam contacts to line side 615. CR41 cam contacts hold M11 relay energized after it has been picked up until 335° in the cycle in which a group change has been detected.

The M11 relay closes the M11-3 contacts to complete a circuit from line side 615, cam contacts CR43, M11-3 relay contacts, pickup coil of M12 relay, wire 660 to line side 616. The hold circuit for the H coil of M12 is back through the M12-1 relay contacts, and CR42 cam contacts, to line side 615. There are shunt contacts

around CR42 cam contacts consisting of the P12-2 relay contacts of the program relay P12. Therefore, when CR42 cam contacts open at 315° in the cycle in which a group number change has been detected the M12 hold relay coil is nevertheless maintained energized until P12 contacts ultimately open, as will be later described.

Referring to Fig. 20c, at 305° when cam contacts CR48 close, which is before CR41 cam contacts open to drop out M11 relay, a circuit is completed from line side 615, wire 661, cam contacts CR48, M11-4 relay contacts now closed, pickup coil of the P1 relay to line side 616. A hold circuit for P1H relay coil is through the P1-1 relay contacts, cam contacts CR50, wire 661, to line side 615. In shunt with P1H is the program cycle control relay CC1. The cam contacts CR50 thus hold P1H and CC1 relay coils energized until about 288° of the next cycle in which a total printing and accumulator reset operation will take place.

During the time that CR3 cam contacts (Fig. 20a) close to attempt to pick up the pickup coil of the R14 automatic start relay R14, M1 relay opens the M1-2 contacts (Fig. 20a). Thus, the R14 relay drops out at the end of the cycle in which a group change is detected when cam contacts CR2 open. Dropping out of the automatic start relay R14 stops card feed during the total taking and reset cycle.

Sub-total and reset control relay

By means of a plug connection 665 the machine is conditioned to print a total from an accumulator and thereafter reset the same. In the cycle in which a change in group numbers has been detected CR58 cam contacts (Fig. 20c) close, thus completing a circuit from line side 615, CR58 cam contacts, CC1-1 relay contacts, plug connection 665, the STR sub-total-reset relay, to line side 616. Thus, from the timing of CR58 (Fig. 21d) it is evident that the STR relay is held energized until about 295° of the next cycle, or the one during which a total printing and accumulator reset occurs.

Other relays for conditioning machine for total printing and accumulator reset operations

These relays are LC, S—, PCC and RN relays and the energizing circuits thereof will be explained as their requirement is needed for the description of the operation of the machine.

At the end of the cycle in which a group number change has been detected CR119 cam contacts close to complete a circuit from line side 615, cam contacts CR119, STR2 relay contacts now closed, S— relay coil to line side 616. CR119 cam contacts keep S— relay closed until about 275° of the cycle during which a total printing and reset occurs. The S— relay closes its S-1 relay contacts, completing a circuit when CR122 cam contacts close between 0-78° of the total printing and reset cycle from line side 615, cam contacts CR122, STR1 relay contacts now closed, S-1 relay contacts now closed, LC relay, to line side 616.

With LC energized total printing takes place in the following manner:

Total printing control circuits

Total printing in the present machine is performed under control of the total readout in conjunction with the combinational code translator described in the section designated "Translator and total digit printing mechanism" which

converts the combinational hole impulse reading derived from the readout sections of the accumulator to a single digit differentially timed equivalent to thereby select a corresponding digit type.

Each readout section comprises a series of digit contact points 661 (Figs. 20d, 20e), a common contact segment 662 and a brush 663 which takes digit positions according to the digit representation of the accumulator order. For simplicity the readouts are shown at digit representing positions which represent a total of —0044. The contact points 661 of like digit values are interconnected by digit impulse transmitting wires 664. In circuit connection with the digit wires 664 marked 9—0 are cam contacts CR97 to CR106, inclusive. These cam contacts transmit combinations of impulses 5, 3, 1, 0 marked alongside of the contacts in Fig. 20d and since the timing is the same as the 5, 3, 1, 0 impulses of CR34 contacts (Fig. 21c) the timing for each individual cam contact CR97—CR106 is not shown. Thus, according to the digit representation of the accumulator readout, combinations of impulses 5, 3, 1, 0 are transmitted. For example, if the brush 663 of a readout order is a 9, the cam contacts CR97 close at times to transmit digit impulses 5, 3, 0 (just like CR34 cam contacts). CR98 transmits impulses 5, 3, CR99, 5, 1, 0, etc., all as designated on the wiring diagram of Fig. 21c. These impulses are directed by a circuit from line 615, CB circuit breaker contacts, CR102 cam contacts (when 4 is the digit in the units order, for example), the 4 digit wire 664, contact point 661, brush 663, common segment 662, STRU relay contacts now closed, LCU relay contacts now transferred, to plug socket 666.

For causing the readout sections to control the related orders of the combinational code translator respective plug connections 667 are made between plug sockets 666 and plug sockets 668. It should also be noted that during 0—90° of the first part of the cycle when cam contacts CR97—106 transmit impulses 5, 3, 0, the LC and STR relays are energized.

Continuing now with the units order, impulses are directed by the related plug connection 667, plug socket 668 (Fig. 20e), through PCCU relay contacts now normal, RNU contacts now normal, translator control magnet 861 of the units order, to line 616. This magnet receives the impulses 3, 0 and as previously described the translator converts the combination of impulses to a 4-digit equivalent to cause the engagement of the type wheel clutch to initiate the rotation of the printing wheel to the 4 digit position. Thus, in each order the combinational impulses 5, 3, 1, 0 are selected by the readout for transmission to the code translator and conversion to a differentially timed digit equivalent. When all printing wheels 860 (Fig. 22a) are at their digit positions printing is effected by transmission of an impulse at the N time.

Referring to Fig. 21c at 165° of the cycle cam contacts CR17 close to pick up the RN relay by an obvious circuit (see Fig. 20c). The RN relay transfers the RNU, T, H, TH contacts (Fig. 20e) so that a second impulse is directed to all orders of the translator control magnets 861 by a circuit from line 615, cam contacts CR80, the U, T, H, TH relay contacts of RN relay now transferred, to the respective translator control magnet 861, to line side 615.

Thus, printing of the digits of the total occurs. Of course, for left-hand orders of the readout representing a total digit of 0 the customary zero

elimination arrangement prevents printing of such unnecessary zeros. Such feature is not shown herein as it is well known in the art.

Circuits to effect resetting of accumulator

The resetting of the accumulator occurs in the same cycle that the total is printed but during the latter part thereof and utilizes differentially timed electrical stop impulses derived from the translator. The start impulses are directed to each start magnet of the accumulator to rotate the accumulator wheel in the additive direction from its digit position to the reset position, which, in the present machine, is the digit 9 position. The stop impulses derived from the translator are directed at such times that the 9 complement of the digit standing on the accumulator wheel is additively entered to thereby bring each wheel to 9.

It is preferable to derive the stop impulses under control of the type wheel clutches, each of which it will be recalled is engaged under control of the combinational impulse translator, so that the engagement of the printing wheel clutch to rotate the printing wheel to a selected digit position is concurrent with the transmission of the stop impulse sent to the stop magnet. Reverting to Figs. 22a and 22b it will be recalled that the combinational code translator causes a movement of the link 363 at differential points in the cycle, as is indicated in Fig. 21b. This causes the engagement of the printing wheel clutch at a differential time and after the engagement is effected type wheel contacts 672 (Fig. 22a) are closed at differential points in the cycle to transmit a stop impulse to the accumulator stop magnet SM of the same order.

Referring to Fig. 22a the plate 898 has an inclined cam edge 670 which cooperates with and rocks the double arm 896 shortly after the clutch engagement has been effected. The lower arm 671 of double arm 896 bears against the top blade of contacts 672. Thus, it is evident that after the engagement of the accumulator wheel clutch the slight clockwise movement of double arm 896 will close contacts 672. This closure occurs, of course, after the clutch has been engaged and the times that contacts 672 are closed to transmit differentially timed impulses 0—9 are shown in Fig. 21b.

Before the circuits for transmitting the stop impulses are explained, the impulsive circuits for energizing the start magnets SM of all denominational orders will first be described. Referring to Fig. 20c, it will be recalled that the S— relay is picked up at the last part of the cycle in which a group number change has been detected and CR119 cam contacts maintain the energization of this relay during the total printing and reset cycle up to about 275°. Therefore, referring to Fig. 20d, when CR85 cam contacts close at about 140° of the cycle a circuit is closed from the line side 615, cam contacts CR85, STR3 relay contacts now closed, through the S—, U, T, H, TH relay contacts now closed, to each of the AM start magnets of the four denominational orders of the accumulator shown herein, to line side 616. This will cause the engagement of all accumulator wheel clutches and if any accumulator wheel stands at any other digit position than 9 the rotation of said accumulator wheel will be initiated to bring it by a movement which is the complement of the digit on the wheel to a 9 digit reset position.

During the rotation of the accumulator wheels

stop impulses are directed to the SM stop magnets by a circuit now to be described. By an obvious circuit shown in Fig. 20c, when CR15 cam contacts close between 100-315° of each cycle the PCC relay is energized to transfer its U, T, H and TH relay contacts. The stop impulse circuit is from the line 615, through cam contacts CR82 which are closed between 116° and 273° during the differential times that the type wheel contacts 672 are closed, thence through the respective U, T, H, or TH relay contact of the PCC relay now transferred, to the plug socket 668, related plug connection 667, plug socket 666, through the respective U, T, H, and TH relay contacts of the LC relay now deenergized, to each SM stop magnet, to line 616.

Recalling that it was assumed that the accumulator represented 0844, with the brush 663 standing at the 4 digit position the contacts 672 of this order will be closed at 225°. However, the start impulse directed by CR85 cam contacts will have moved the accumulator wheel from 4 to 9 or five steps at the time that the stop magnet SM receives the impulse from the type wheel contacts 672. Thus, the accumulator wheel will be stopped at the 9 digit position. The operation is the same for the tens order where 4 was assumed to be the total digit representation in this order. However, for the hundreds and thousands orders it was assumed that 0 is represented in each order, which is indicative of a positive or debit balance. The start impulse to the start magnets AM of such orders will initiate the 9 steps of movement. The printing wheel clutch is engaged to rotate print wheel 860 counterclockwise at about the same time that the print wheel arm 881 is rocked to rotate print wheel 860 clockwise, as a result of the N printing impulse. This will cause the printing from the 0 digit type. Engagement of the printing wheel clutch causes a later closure of contacts 672 sending a stop impulse to the SM magnet after the accumulator wheel has rotated nine steps to bring the wheel to the 9 digit position.

If a wheel stands at 9 (indicative in left-hand orders of a negative or credit balance) the closure of contacts 672 to send a stop impulse at about 140° after the print wheel clutch is engaged to select the 9 type is coincident with or slightly earlier than the start impulse transmitted to the AM magnet by CR85 cam contacts. This prevents engagement of the clutch and the wheel remains at 9.

Reset test circuit

At the end of each cycle and, of course, at the termination of the cycle in which the accumulator has been reset, a test circuit is operative to determine whether the accumulator wheels have gone to their reset positions which, in the present machine, is the 9 digit position. If the machine has been conditioned for total taking and reset operations this test circuit will be operative to determine the further operation of the machine, thus continuing with card feeding for the next group of cards, or in the event of an error, stop card feed and indicate this faulty operation in a suitable manner.

It is explained that the complementary movement given to each accumulator wheel to bring it to a reset position also moves the readout brush 663 of the same order a corresponding extent of movement so that if the accumulator wheel comes to the reset or 9 digit position the brush 663 will, of course, also come to the 9 digit position resting on the 9 segment 661 and the

units carry control contacts 739 and 741 (Fig. 18) will be in contact with each other.

Referring now to Figs. 20d and 20e, the transfer control contacts 739, 741 for the four denominational orders shown are connected in series circuit connection so that when all orders represent 9, which is when each contact blade 739 makes contact with a related contact point 741, a pickup circuit will be completed from line 615 through cam contacts CR70 which close at the end of the cycle, thence through the four sets of contacts 739, 741, SZB pickup coil, to line side 616. A hold circuit for the H coil is provided by a circuit from line 615 through the H coil, SZB1 relay contacts, cam contacts CR73, to the line side 615. CR73 holds the energization of SZB over to the greater part of the next cycle. In Fig. 20e there is shown an error indicating relay RE which has its pickup circuit conditioned for causing energization of its pickup coil during total taking and reset operations and if all accumulators are at reset position. The conditioning of this circuit is effected under control of the SCT relay (see Fig. 20c). The pickup coil of SCT is in shunt with the S— relay coil and, therefore, is energized by the same energizing circuit when cam contacts CR119 close at the end of the cycle. A hold circuit for the H coil of SCT is from the line 616 through the H coil, SCT1 relay contacts, CR74 cam contacts, to the line 615. CR72 cam contacts are closed at the end of the cycle to attempt to energize the RE relay by the following circuit: From the line 615, through CR72 cam contacts, SCT2 relay contacts now closed, through the SZB2 relay contacts which are open if the accumulator has been reset in all orders, or are closed if any order is not at the 9 digit position after a reset operation, to the pickup coil of RE relay to line side 616. If RE coil has been picked up the hold circuit is from the line 616, through H relay coil, RE1 relay contacts, wire 613 which extends back as shown in Fig. 20a, through the stop key contacts 624, wire 623, to the line side 615.

It is now evident that if all orders of the accumulator are restored to the reset position the RE relay will not be picked up and the machine will continue with normal operations of the machine. It is well known that in the type of machine in which the present invention is incorporated that after a total taking operation the machine will continue with feeding of cards and the accounting operations will continue for the next group until a group change has been detected.

To continue with card feeding operations of the machine when an error is not detected it is, of course, necessary to drop out the M12 relay 60 which, it will be recalled, is held energized by relay contacts P12-2 (Fig. 20c). This will allow M12-2 contacts (Fig. 20a) to close so as to complete the pickup circuit to the R14 automatic start relay. During the total taking and reset cycle a circuit is completed from line side 615, wire 661, through M12-2 relay contacts (Fig. 20c) now transferred, P1-3 contacts now closed, RE5 transfer contacts now in normal position (since no error in reset has been detected) 65 through P13-2 contacts now closed, cam contacts CR132 to the pickup coil of P12. A hold circuit for P12 relay is maintained by a circuit from the line 616, through the H coil of P12, P12-1 relay contacts, cam contacts CR46, to the line side 615. When P12 relay is energized and

held energized it opens the P12-2 contacts to deenergize M12 relay. The hold circuit for P12 is held longer by cam contacts CR46 than the time that the CR42 cam contacts are closed, thus maintenance of the opening of the supplemental hold circuit longer than the closing of the hold circuit by CR42 will finally result in the deenergization of the M12 relay coil.

Reset error circuit

There may be numerous reasons why an accumulator will not come to a reset position in all orders and may be caused, for example, as a result of the omission of a plug connection 667. If, for example, the operator failed to make this plug connection in the units order the normal start impulse from CR85 cam contacts will be directed to start magnet AM of this order but due to the omission of the plug connection an impulse will not be directed to the stop magnet SM of the units order.

The brush 663 of the readout will first come back to the digit representation of "3" and the accumulator clutch will be disengaged by the first mechanical knockoff pin 752. However, due to the well known units carry devices which are incorporated in the present basic machine the units carry to the order in which "3" is represented will change the corresponding readout position to "4." Hence, contacts 739-741 in the units order will be open, SBZ relay is not energized, SBZ2 relay contacts will remain closed and RE relay will be picked up. There will now be described how the normal card feeding operation of the machine is changed and a second total printing cycle is carried out upon the discernment of an error in reset operations.

Understanding that when an error has been detected the RE relay is energized during the first total printing and reset cycle when cam contacts CR72 close at 347°, a circuit will be completed when CR133 contacts close at 5° of the next cycle, (RE being held indefinitely) which extends from line 615, wire 661, M12-2 transfer contacts now normal, RE5 contacts now transferred because an error has been detected, RE4 contacts now closed for the same reason, CR133 cam contacts, P14-2 contacts, the pickup coil of P13 relay to line side 616. The hold circuit for P13 is from line 616, P13H relay coil, P13-1 hold contacts, cam contacts C45, wire 661, back to line side 615. This will hold the P13 relay energized until 315° of the cycle following the total printing and reset cycle, which may be called an idle cycle. At 305° of this idle cycle when CR48 cam contacts close, a circuit will be completed from the line side 615, through P13-2 relay contacts now closed, the pickup coil of P1 to the line side 616. Thus, the P1 coil is picked up and held by CR59 cam contacts and by repetitions of the operations previously described the machine is again conditioned to go through an ensuing or second total printing and reset cycle carrying out operations previously described.

Assuming that all orders of the readout were brought to a 9 position except the units order which still represents 4, it will be seen that in this ensuing cycle the total will again be printed and a 4 will be printed in the units order printing column. This will give a printed indication that there is an error in resetting the units order.

The reset test circuit previously described will again be operative but will be ineffective because the RE relay has already been energized and maintained energized indefinitely through the

hold circuit passing through the stop key contacts 624.

An interlock circuit is provided, however, to prevent a following third total printing and reset cycle. This is effected by the P14 relay. At 273° of the so-called idle cycle cam contacts CR47 close while P13 relay is still energized to complete a circuit from line 615, through CR47, cam contacts P12-3 contacts now closed, P13-3 contacts now closed, wire 614, RE3 relay contacts now closed, pickup coil of P14 to the line side 616. A hold circuit is maintained from line side 616, through P14H relay coil, P14-1 relay contacts, wire 673, stop key contacts 624 to the line side 615 to thus keep R14 relay energized indefinitely. Thus, it is evident that during the second total printing and reset cycle following the one in which an error has been detected the impulse circuit to P13 cannot be completed a second time through the circuit previously described because of the opening of contacts P14-2.

If so desired, a signal light SL (Fig. 20e) may be shunted across the hold coil of the RE relay and have it located in view of the operator so that the light will indicate that there has been an error. The second printed total will indicate the denominational order of the accumulator in which the error has occurred.

Opening of card feed circuit upon ascertaining an error

It is, of course, desirable under such circumstances to stop feeding cards so that the reason for the error can be located and corrected.

Referring now to Fig. 20a, it will be seen that the impulse circuit to R13 relay is through the RE2 relay contacts. Energization of RE relay upon locating an error in reset will open RE2 contacts and therefore the R13 relay is not energized and R13a contacts open so that R14 relay cannot be picked up. It will be remembered that the R14 relay has its R14b relay contacts in the impulse circuits for the FP, FG, RP, RG and CF clutch magnets. Therefore, none of the four clutches in the card feed mechanism will engage and further the main card feed clutch magnet CF will not be energized so that the complete card feeding unit will be inoperative and, therefore, no cards will be fed.

When the stop key is depressed the hold circuits for RE and P14 are broken thus conditioning the machine so that card feed may be resumed by depression of the start key and closure of its contacts 617.

While there have been shown and described and pointed out the fundamental novel features of the invention, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In an accounting machine wherein total printing and accumulator reset operations are effected, the combination of an accumulator comprising a plurality of denominational ordered accumulator elements which represent the digits of a calculation, means under control of said elements to record the digits standing on said accumulator elements, means for clearing out and resetting said elements to restore all orders to a reset condition, means for testing and detecting the reset condition of the elements in all orders,

and means effective upon detecting the failure of a reset condition in at least one order to repeat the operation of said recording means to record the digits standing on said accumulator including the order in which said accumulator failed to be restored to a reset condition.

2. In an accounting machine wherein total printing and accumulator reset operations are effected, the combination of an accumulator comprising a plurality of denominationally ordered accumulator elements which represent the digits of a calculation, means for reading out said elements, means under control of said reading-out means to record the digits standing on said accumulator elements, means for clearing out and resetting said elements to restore all orders to a reset condition, means for thereafter testing and detecting the reset condition of the accumulator elements in all orders, means effective upon detecting the failure of a reset condition in at least one order to repeat the operation of said reading-out means to cause said recording means to record the digits standing on said accumulator including the order in which said accumulator failed to be restored to a reset condition, and to repeat the operation of said clearing out and said resetting means.

3. In an accounting machine wherein total printing and accumulator reset operations are effected, the combination of driving means, an accumulator comprising a plurality of denominationally ordered accumulator wheels which represent the digits of a total, means for clutching each wheel with said driving means, a readout associated with said accumulator wheels, total printing means comprising a print wheel for each accumulator wheel, a print wheel clutch for each print wheel and means under control of said readout to engage each print wheel clutch with said driving means to initiate the rotation of said print wheel to digit positions represented by said readout, resetting means comprising means to engage all of said accumulator clutches with said driving means at the same time to rotate each wheel toward reset position and means under control of said printing wheel clutch when engaged to disengage the related accumulator wheel clutch when the related accumulator wheel is at reset position, means for thereafter testing the reset position of each accumulator wheel, and means effective upon detecting the failure of a reset position of any accumulator wheel to repeat the operation of said total printing means to thereby print the digits standing on said accumulator including the wheel which failed to be restored to a reset condition.

4. In an accounting machine wherein total printing and accumulator reset operations are effected, the combination of driving means, an accumulator wheel, means to represent the digit standing on said wheel, an accumulator wheel clutch, a print wheel, a print wheel clutch, total printing means comprising means under control of said digit representing means to engage said print wheel clutch to initiate the rotation of said print wheel to a digit position represented by said representing means, resetting means for said wheel comprising means to engage said accumulator wheel clutch to rotate the accumulator wheel towards a reset position, and means under control of said print wheel clutch when engaged to disengage the accumulator wheel clutch when said accumulator wheel is at reset position, means for testing the reset position of said wheel, and means effective upon detecting that said wheel is

not at reset position to repeat the operation of said total printing means.

5. In an accounting machine, the combination of an accumulator comprising a series of digit representing wheels which represent the digits of a total of a series of item entering operations, a 0-9 representing readout associated with each wheel of said accumulator, a combinational impulse code translator for converting combinational impulses to a single differentially timed equivalent 0-9, means under control of said readout to transmit combinational impulses to said translator according to the 0-9 digit represented, total printing means comprising a print wheel and means under control of said translator to initiate rotation of said print wheel to a digit position corresponding to said readout and said differentially timed equivalent, resetting means comprising means to initiate rotation of said accumulator wheels at a fixed time and means under control of said print wheel to terminate rotation of said accumulator wheels when they arrive at a reset position, means thereafter testing the reset position of each of said wheels to detect whether any of said wheels has not been restored to a reset position, means under control of said testing means upon detection that at least one wheel has not been restored to a reset position to repeat the operation of said means to transmit combinational impulses under control of said readout to said translator and the operation of said total printing means to print the digits standing on said accumulator wheels including the wheel which failed to be restored to a reset position after a reset operation.

6. In a machine wherein cards are fed successively and in classified groups and a total taking and accumulator reset operation is automatically initiated upon a group number change, said machine including means to successively feed said cards, means to analyze said cards, and group control means to detect a group number change in successive cards, the combination of an accumulator having accumulator wheels, means for operating each of said accumulator wheels to bring them to reset position, means for reading out the total standing on each of said accumulator wheels, means under control of said reading out means to print the digits of the total, means under control of said group number control means when a group number change has been detected to effect the operation of said reading out means to print a total and thereafter operate said operating means for said accumulator wheels to restore them to reset position, means for testing each accumulator wheel to ascertain whether each is at said reset position, and means under control of said testing means upon detecting the failure of one wheel to be restored to reset position to reinitiate and effect a second operation of said reading out means to print the digits standing on said accumulator wheels including the digit standing on the wheel which was not restored to zero.

7. In a machine wherein cards are fed successively and in classified groups and a total taking and accumulator reset operation is automatically initiated upon a group number change, said machine including means to successively feed said cards, means to analyze said cards, and group control means to detect a group number change of cards, the combination of an accumulator having accumulator wheels, means for operating each of said accumulator wheels to bring them to reset position, means for reading out

the digits of the total standing on each of said accumulator wheels, means under control of said reading out means to print the digits of the total, means under control of said group number control means when a group number change has been detected to effect the operation of said operating means for said reading out means to print a total and thereafter operate said accumulator wheels to restore them to reset position, means for testing each accumulator wheel to ascertain whether each is at said reset position, means under control of said testing means upon ascertaining that all wheels have been restored to reset position to initiate the operation of said card feeding means, and means under control of said testing means upon detecting the failure of one wheel to be restored to reset position to reinitiate and effect a second operation of said reading out means to print the digits standing on said accumulator wheels including the digit standing on the wheel which was not restored to zero and to suspend the operation of said card feeding means.

8. In a machine wherein cards are fed successively and in classified groups and an accumulator reset operation is automatically initiated upon a group number change, said machine including means to successively feed said cards, means to successively analyze said cards, and group control means to detect a group number change in said cards, the combination of accumulator wheels, means for operating said accumulator wheels to bring them to reset position, means for reading

out the total standing on said accumulator wheels, means initiated by said group number control means when a group number change has been detected to effect under control of said reading out means the operation of said accumulator wheel operating means to restore said wheels to reset position, means for testing said accumulator wheels to ascertain whether each is at said reset position, and means under control of said testing means upon detecting the failure of one of said wheels to be restored to reset position to reinitiate and effect a second operation of said resetting means.

9. In an accounting machine wherein total printing and accumulator reset operations are effected, the combination of an accumulator, means under control of said accumulator to record the digits of a calculation, means for clearing out and resetting said accumulator to restore all orders to a reset condition, means for testing and detecting the reset condition of said accumulator, and means controlled by said testing means upon detecting the failure of a reset condition in at least one order to cause a repeat operation of said recording means to record the remaining amount standing on said accumulator after a reset operation.
